UNITED STATES PATENT OFFICE

ALWIN B. BACHMANN, OF BROOKLYN, NEW YORK, ASSIGNOR TO KEARNEY & TRECKER CORPORATION, OF WEST ALLIS, WISCONSIN

MILLING MACHINE

Original No. 1,672,744, dated June 5, 1928, Serial No. 471,061, filed May 20, 1921. Application for reissue filed May 16, 1930. Serial No. 453,000.

This invention relates to milling machines, and to a method of operation of such machines. As to the machine itself, my invention contemplates, among other objects, the provision of a milling machine free from deficiencies which inhere in prior milling machines having a reciprocating or rotating work table, by which the work is fed in a straight line under the cutting tool and re- turned to initial position, or continuously fed in a circular path under the cutting tool.

The prior milling machines referred to comprise several types, which it will be necessary to briefly mention in order to indicate the object of the present invention, just stated.

The prior milling machines here referred to may be classed in two groups—one employing a reciprocating work table, whereby the work piece is fed in a straight line under the cutting tool and returned in the same path to initial position, and the other employing a rotating work table, whereby a plurality of work pieces placed off center thereof will be fed in a circular movement under the cutting tool, and which work pieces successively return to initial position where they can be removed and new work pieces placed upon the table.

The development of these machines shows the tendency in the art to reduce the non-cutting or non-productive time and to simplify the functions of the operator by performing the different movements of the table automatically. Thus, in both types, the feed has been rendered intermittent, by means of adjustable dogs and cooperating feeding means, whereby the feed or movement of the table under the cutter may be varied from a slow feed, when a work piece is in position beneath the cutter, to a fast traverse, to hasten the advance of the next work piece to the cutter, then a slow feed again while the last mentioned work piece is undergoing the cutting operation, and again a rapid traverse to hasten the advance of the next work piece to cutting position; and, finally, in the case of a reciprocating slide, a rapid return after all the work pieces have advanced beyond the cutter, back to the initial position.

While, in the second type, employing a ro-

tating work table, work pieces may be set or removed while the table is rotating and a work piece passing under the cutter, this type can advantageously be used only with work pieces of circular shape or for face milling, since the work pieces upon the rotating table transcribe a circular path under the cutting tool. Another disadvantage of this type is the necessity of employing numerous work-holding fixtures, the expense of which is warranted only when milling parts in very large quantities.

A third type has been developed in an endeavor to eliminate the idle time occurring in the first type of machine by the necessity of stopping the work table when setting or removing a work piece, by the employment of two work tables mounted upon a swivel, upon one of which the work is being cut while new work is being set upon the other, the two tables being successively swivelled into working relation to the cutter. This third type, however, requires a multiplication of parts which is in itself objectionable and further tends to inaccuracy of work; and moreover, requiring so large a turret for the two swivelling work tables or so great an overhang of the tables upon the turret as to form a source of inconvenience to the operator.

One of the objects contemplated by the present invention is to provide a single work table of the reciprocating type in its feed, traverse and return, and to provide means for removing a finished piece of work and setting a new piece while the table is in motion, and without the multiplicity of parts employed in the third type referred to.

Another object of the present invention is to provide in one machine the various movements of the work in feed, traverse and return hitherto possibly only in the several types of machines of the prior art, and thereby to combine in one compact machine the certain distinct advantages of the several types of the prior art. Thus, each of the heretofore mentioned types of machine offers certain advantages in handling certain classes of work, but a class of work which could be advantageously handled by one type of machine could not generally be advantageously

55

or economically handled by another type. For example, the rotating table type of machine is employed, as heretofore stated, for work pieces of circular shape or for face milling, which work could not be so advantageously or economically done upon the straight reciprocating table type of machine. Therefore, no one of the heretofore mentioned types of machine offers the advantage of being always able to employ the most efficient and most economical way of milling for all classes of work. It is, therefore, an object of the present invention to provide a work table and means for so moving that work table, that the single compact machine may be employed in performing substantially the same movements of the work pieces as in any one of the heretofore mentioned types of machine.

Another object of the invention is to accomplish a return of the finished work pieces to initial position without such return describing a path of the work pieces underneath the cutter, and thus avoiding any possible marring or injury to the finished work pieces by the cutter, such as may possibly occur in the straight reciprocating table type of machine hereto referred to in which the work table in its return to initial position returns the finished work piece again underneath the cutter.

Still another object of my invention is to provide for a feeding and traverse of the work table in either direction underneath the cutter.

Further objects of my invention will appear from the detailed description of a preferred embodiment thereof later to be given.

To accomplish the objects heretofore stated and other objects which will later appear in the detailed description of a preferred embodiment of my improved machine and of various methods of operating thereof, my improved machine includes a work table and driving means therefor whereby any of the following methods of operation may be performed at will:

- (1) A reciprocation of the table in a straight path underneath the cutter,
- 50 (a) with a slow feeding movement continuously in either direction, or
- (b) with an intermittently slow feeding and rapid traversing movement continuously in either direction, or
- 55 (c) with an intermittently slow feeding movement and a rapid traverse and a rapid return;
- (2) A rotation of the table without reciprocation either slowly or rapidly continuously, or intermittently with a slow feed and rapid traverse;
- (3) A reciprocation of the table in forward feeding and traversing movement and return to initial position, and then a partial rotation

or indexing of the table to present a new work piece in proper relation to the cutter;

(4) A reciprocation of the table in feeding and traversing movements under the cutter and after the last work piece has advanced beyond the cutter to finished position, and indexing movement of the table simultaneously with the return movement of the table in its reciprocatory path to provide a new work piece in proper relation to the cutter.

By the movements mentioned in paragraph (1) above, all the advantages of the reciprocating table type of milling machine are present, while by the movements set forth in paragraph (2), all the advantages of the rotating table type of milling machine are present, and by the movements set forth in paragraphs (3) and (4), all the advantages of the double swivel table type of machine are present, without the disadvantages thereof heretofore mentioned.

The partial rotative movement termed an indexing movement of the table mentioned in paragraphs (3) and (4) is distinct and for a different purpose than the complete rotation of the table set forth in paragraph (2). When the movements set forth in paragraphs (3) and (4) are employed, any desired number of work pieces may be placed upon the table in such symmetrical relation to the center of the table that when the table is reciprocated to pass one or a plurality of work pieces of one side of the center beneath the cutter, partial rotations of the table through the proper degrees will successively bring the

symmetrically placed work pieces on the opposite side of the center from the first mentioned work pieces which have been finished, into position to be operated on by the cutter when the table is again advanced in a straight line movement. Thus if but two work pieces are placed upon the table one on one side of the center in position upon the first reciprocation of the table to pass beneath the cutter and the other work piece is placed on the opposite side of the center of the table an indexing of the table through 180 degrees, after the first work piece is finished, will bring the second work piece in position whereby the next reciprocation of the table will bring that work piece beneath the cutter. If a plurality of work pieces are symmetrically placed upon the table, the indexing movement of the table will be through a correspondingly less number of degrees.

Performing the return movement of the table in its reciprocatory path before performing the indexing movement of the table to present a new work piece for the cutter, as set forth in paragraph (3), is of great advantage in all cases where the removing of the finished work and the setting of a new piece of work upon the table takes a longer time than the forward cutting and return movement of the table. In cases, however,

where the forward cutting and return movement of the table takes a longer time than removing work already finished from the table and setting new work thereon, it is of 5 greater advantage to perform the indexing of the table during its return movement in the reciprocatory path, as set forth in paragraph (4) above.

This simultaneous indexing movement and 10 return movement of the table, in addition to the saving of time involved, also returns the finished work piece upon the table to initial position in a path, due to the indexing movement of the table, which avoids a return 15 passage under the cutter, and therefore obviates the possibility of a marring of the finished work.

The machine provides for the various movements referred to either automatically 20 throughout the progress of the movements after an initial hand adjustment of dog tripping mechanism or by hand operating mechanism operated at will at the various stages of the desired movements.

25 In the foregoing a general outline of the various table movements has been given, but a still greater variety may be obtained, as will later appear from a detailed description of an illustrative embodiment of the invention and the methods of operation thereof, by first selecting a movement best suited for a certain class of work and then adjusting the automatic trip dogs later to be referred to, which dogs cooperate with the various 30 movement transmitting means, or by manual manipulation of the mechanisms, later to be referred to, cooperating with the movement transmitting means. All these movements, in addition to the provision of hand operation 35 during the progress of the cycle of the movements, may thus be automatically performed if desired, and the operator has then only to attend to the removing of the finished work pieces and the placing of the new ones.

40 The various features of my invention will be more fully set forth in the description, and the accompanying drawings forming part of this specification, of an illustrative embodiment thereof and of various methods 45 of its operation, but it is to be understood that my invention as to the machine is capable of embodiment in many different forms and my invention as to the methods of milling is not limited to the illustrative machine. While, 50 therefore, I shall illustrate my invention by the best physical embodiment known to me, such embodiment is to be regarded only as typical of many possible embodiments, and my invention is not to be confined thereto.

In the drawings like characters of reference denote corresponding parts throughout all of the views, of which—

10 Figs. 32, 33 and 34 are diagrammatic views showing the travel of the work upon the work table around the cutter through the simultaneous movement of the reciprocating slide and the work table in indexing.

15 As will be obvious from an inspection of the drawings, the various figures thereof are drawn to varying scales for purposes of clearness.

20 As a preliminary to the more detailed description of the machine constituting the illustrative embodiment of my invention, it may be stated that the work table, circular in form, is mounted for rotation upon a reciprocating slide, which slide in its reciprocating 25 movement describes a straight path longitudinally of the machine, as viewed in Fig. 1, and at right angles to the plane of the drawing as viewed in Fig. 2, beneath the cutting tool shown in Fig. 2.

30 When the work table is to be reciprocated without rotation, to accomplish the functions, among others, of a milling machine of the type hereto referred to in paragraph (1), the circular table is to be locked to the reciprocating 35 slide by means of a locking pin, which may be withdrawn manually by the operator at will or may be automatically withdrawn in a manner hereinafter set forth, so as to set the circular table free for complete rotation in milling or for partial rotation in indexing. 40 When the work table is locked to the slide and continuously reciprocated back and forth therewith, all of the functions of the first mentioned type of milling machine may be 45 accomplished.

In addition to this continuous reciprocation of the slide with the work table locked thereon, at either extremity of movement of the slide, the locked pin may be withdrawn 50 and the work table caused to partially rotate, in what is here termed an "indexing" movement, and thereafter again locked in position on the slide to position a different portion of the work table in the path of the cutter, thus accomplishing the functions not heretofore accomplished by the types of milling machines already referred to.

Considering now the circular work table locked to the slide, work, fastened to the table 55 some distance off center, may be cut by imparting a feeding movement in a straight line to the slide. During this process of cutting, work can be set at some other place on the table and such a position as will bring the 60 work in proper relation to the cutter when the

work table is indexed after the first work piece has been finished. For example, for two pieces of work, placed off center and symmetrically with respect to the center of the table, and one on that side of the center in line with the cutter, and the other on the opposite side of the center, when the slide has been fed forward with the table locked thereto so as to bring the first mentioned piece of work beneath and beyond the cutter so as to be finished thereby, the slide with the work table still locked thereto may be returned to initial position and thereafter the lock pin withdrawn and the table indexed 180 degrees to bring the unfinished work into that path described by the first mentioned work, the table again locked to the slide and the slide again advanced to feed the table and the new work piece beneath the cutter, during which advance of the new work piece, the finished work piece may be removed and another work piece placed upon the table in the position as before. Or, after the table has completed its first advance to bring the first mentioned work piece beneath and beyond the cutter to finished condition, the locked pin may be withdrawn and the indexing movement started simultaneously with the return of the slide and table to initial position, thus saving time in the indexing, and accomplishing the additional function of returning the finished work piece in a circular path avoiding the cutter instead of a return along its original path as in the first mentioned operation. When three work pieces are symmetrically placed upon the table, the indexing movement referred to will be 120 degrees, and correspondingly less in proportion to the number of work pieces.

The slide may also be maintained stationary, the work table released from its locked relation thereto, and the work table rotated thereon for continuous milling work pieces in a circular path, and the machine as thus operated accomplishes all the functions of the second type of milling machine heretofore referred to.

It will be observed from this outline that there are three possible driving movements; the reciprocatory movement of the slide in a straight path beneath the cutter, the continuous rotation of the work table thereon for circular milling and the partial rotation of the table or indexing movement. All three of these drives are taken from a single main driving shaft. In the first two drives, provision is made for a slow feed, while the work is passing the cutter and a quick traverse to advance the work piece to cutting position, and a quick return of the table to initial position, while the third drive, for indexing, is one of constant speed. Provision is also made for setting these three drives into operation either manually or automatically through trip dogs adjustable upon

the reciprocating slide and the rotating table and cooperating with the driving mechanism in the body of the machine; and like provision is made for locking or releasing the rotatable table upon this slide either manually or by adjustable trip dogs.

By the adjustment of the trip dogs a great variety of automatic timings of the movements of slow feed, rapid traverse, return of the table and indexing of the table, can be had to correspond to the necessities of the work.

Means are also provided for disconnecting the power drives for the reciprocation of the slide and the rotation and indexing of the work table, and for manually driving these parts, such provision being of advantage particularly in setting the trip dogs for the various timing operations when the power drive is restored.

The slow and fast feeds are not only taken from a single main driving shaft, as already stated, but such movements are also transmitted to a single intermediate transmission shaft from which single intermediate transmission shaft branch driving shafts and cooperating driving mechanisms transmit the drives to the reciprocating slide and the rotatable table in circular milling and in indexing.

In order to provide as few clutch operations as possible, provision is made, by way of a differential speed transmission mechanism, for continuing the slow drive and superimposing thereon at will the rapid drive.

To provide for as few operating parts as possible in a machine of this character, provision is also made for a single reversing mechanism operative upon both the slow and fast movements in the milling drives mentioned, namely, the straight drive for the reciprocating slide for straight milling and the drive for rotating the work table in circular milling.

To meet the various conditions under which the cutting tool has to work, provision is also made by way of change gears, to vary the slow or fast drive.

As already stated, two movements are given to the rotatable work table; one, a continuous rotation in circular milling, and the other, a partial rotation, in indexing, during both of which movements, it is obvious that the table must be unlocked for movement upon the slide; and provision is made for locking the table against the indexing movement while a continuous rotary movement is being performed, and vice versa,—that is, complementary locking in the indexing and circular table driving mechanisms.

The detailed description of the illustrative embodiment of the invention which is to follow relates to these various mechanisms thus outlined.

Proceeding now to a detailed description of

the illustrative machine, numeral 1 (Fig. 1) denotes in general the frame or housing of the machine. At one side thereof, the left-hand side as viewed in Fig. 2, is the spindle column 2, while the right-hand side thereof provides a housing for the various driving mechanisms, later to be described, and a support for the reciprocating slide 60 and the rotatable table 61 thereon, later to be described in detail.

The cutter spindle column and the power transmission therethrough to operate the cutter spindle may be of the usual or any preferred construction and the details thereof constituting no part of my invention, are not deemed essential to illustrate or describe.

The main power shaft of the machine is indicated by the numeral 3 (Fig. 2), operated in any suitable manner, a pulley 3' being here illustrated, and the power being transmitted thereto from any desired prime mover.

Motion for the various driving mechanisms is taken off the main pulley shaft 3 (Fig. 2), which is running at a constant speed, and transmitted to pulley 4 of the main drive or feed shaft 5, which at one end is journaled in a bearing 6 on the frame 1 (Fig. 2) and at the other end is journaled in a gear box 10 (Fig. 26).

Pulley 4 is mounted loose on the shaft 5 and is adapted to be connected by means of a friction clutch 7 (Fig. 2) to said shaft, to transmit rotary movement to said shaft. The friction clutch is under the control of a foot treadle 8, which is located conveniently to the operator, as shown in Fig. 2, and which foot treadle is connected with the clutch 7 by rod 8' and lever 9. Feed gear box 10, shown in outline in Fig. 1, is bolted to frame 1, and is provided with two bushings 11 and 12 (Figs. 1, 5 and 26), which form two additional bearings for the shaft 5 which extends through the gear box, as shown in Fig. 26.

Rotatably mounted on 11, as shown in Figs. 5 and 26, is a spur gear 13, which is provided with clutch teeth 14. Numeral 15 (Figs. 5 and 26) indicates a cooperating toothed clutch turning with and sliding on shaft 5. On the other end of the shaft is mounted and fixed thereon a worm 16 (Fig. 5) which meshes with worm wheel 17 (Figs. 5 and 26). This worm wheel is provided with clutch teeth 18 and is free to revolve on shaft 19 (Figs. 9 and 26) which is journaled in bearings on the gear box 10. Clutch 20 turns with and slides on shaft 19 and can be brought into mesh with worm wheel 17. A bevelled pinion 21, fixed on shaft 19, meshes with the bevelled gear 22 (Figs. 4 and 26) which is mounted loose on bushing 23. Fixed to this bevelled gear is a change gear 24, which transmits motion over the change gears 25, 26 and 27 to shaft 28. This shaft is journaled in bushing 23, which bushing is secured

in a fixed position in gear box 10, as shown in Fig. 4.

It is obvious from the foregoing, and particularly from an inspection of the layout of the gearing as shown in Fig. 26, that rotation transmitted to the shaft 5 will be transmitted at a reduced speed to the shaft 19 through the worm 16, worm wheel 17 and clutch 20, and therefrom to the shaft 28 through the bevelled gears 21 and 22 and the series of change gears 24, 25, 26 and 27.

In a similar manner motion is transmitted from shaft 5 to shaft 36 (Figs. 4 and 26) by means of gear 13, when the clutch teeth 14 and 15 are in engagement therewith, over the idler gear 29, to spur gear 30, which is mounted loose on bushing 31, to change gear 32 fixed to spur gear 30, and through the change gears 33, 34 and 35, to the said shaft 36.

Shaft 36 is journaled in bushings 31 and 38, both of which are secured in a fixed position in gear box 10 as shown in Figs. 4 and 26.

25 Slow and fast speed transmission from a single driving shaft

It is obvious from the foregoing, and particularly from an inspection of Fig. 26, that slow speed rotation is transmitted from the shaft 5 to the shaft 28, and rapid speed rotation from the shaft 5 to the shaft 36. These two speed transmissions form the origin for the slow movement of the work table in feeding the work piece beneath the cutter and the rapid movement of the work table in traversing a work piece to cutting position or in returning the table, which has already been referred to.

40 Transmission of slow and fast speed from a single driving shaft to a single intermediate transmission shaft

These two driving movements, slow and fast, are to be transmitted over a single interconnecting shaft to branched driving connections for reciprocating the slide and rotating the work table thereon, to accomplish which a differential speed transmission mechanism is provided to transmit these two rotative movements to the single interconnecting shaft referred to, and a single reversing means is provided for reversing the direction of slow and fast rotation transmitted over the single shaft.

Single reversing mechanism

The reversing mechanism is as follows:— Two bevelled gears 39 and 40 (Figs. 4 and 26), having toothed clutch members 41 and 42 respectively, are mounted loose on shaft 36. Between these two bevelled gears 39 and 40 is located a double toothed clutch 43 turning with and sliding on shaft 36, and designed to fix either of the gears 39 and

40 to said shaft by the alternating opposite throw of this double toothed clutch. Bevelled gears 39 and 40 are in mesh with the bevelled gear 52 (Fig. 26) which is secured to the shaft 53, this shaft being the single interconnecting shaft referred to. The shaft 53 is journaled in bushing 54, which in turn is secured in a fixed position in gear box 10.

Differential speed transmission mechanism

The differential speed transmission mechanism so as to enable the single shaft 53 referred to to partake of the slow or fast speed of rotation is as follows:—Fixed upon the adjacent ends of shaft 36 and shaft 28 (Fig. 26) are the bevelled gears 44 and 45, respectively, which mesh with the two bevelled gears 46 and 47. The latter are mounted loose on the shaft 48, which is in a fixed position in the bevelled gear frame 49 (Figs. 4 and 26). This frame is free to revolve on the ends of the bushings 23 and 38 in which the shafts 28 and 36 are respectively journaled, and is provided with a toothed lock wheel 51 (Figs. 4, 26 and 27). Cooperating with this toothed lock wheel is a pawl 50 which is journaled on stud 55 secured in bracket 56 (Figs. 26 and 27), and which pawl is held in engagement with the lock wheel 51 by means of the spring 57. From the foregoing it is obvious that the gear frame 49 can turn in only one direction, as it is locked against a turning movement in the opposite direction by means of the pawl. Assuming now that clutch 20 is in mesh with the clutch teeth 18 of worm wheel 17, motion is transmitted from shaft 5, which is rotating at a constant speed, to shaft 28, and on account of the reduction of speed through the worm and worm wheel, the rotation of shaft 28 is at a "slow" or a "feed" rate. Assuming, however, that clutch 15 is in mesh with the clutch teeth 14 on spur gear 13 and that clutch 20 is not in mesh with the clutch teeth 18, then motion is transmitted from shaft 5 to shaft 36 only and at a "fast" or "quick" traverse rate. All movements causing the advance of the straight slide 60 and the circular table 61 (Figs. 1, 2, 3, 4, 9 and 28) in either direction, either slow or fast, or intermittently slow and fast, are taken off the single shaft 53, and these movements are imparted to said shaft 53 from shaft 28 and shaft 36, in the manner heretofore stated. If motion is transmitted from shaft 5 over clutch 20 to shaft 28 in one direction, that shown by the arrow in Fig. 26, that rotation is imparted to shaft 36 in the opposite direction of rotation through the bevelled gears 45, 46 and 47 and 44, but the torque of the driving force exerted through shaft 28 tends to turn the gear frame 49 with the lock wheel 51 in the same direction in which shaft 28 is rotating, that is, against the pawl 50 (Fig. 27), thus holding the frame 49 stationary. If, therefore, the rotation of shaft 5 is trans-

mitted only through the worm 16, worm wheel 17, clutch 20, and the various cooperating gears heretofore referred to to shaft 28, then that reduced speed of rotation of shaft 28 is transmitted to shaft 36 and from thence through the bevelled gears 39 or 40 and 52 to the single interconnecting shaft 53, and the direction of rotation of that "slow" speed is controlled by the shifting of the clutch 43 to either of the bevelled gears 39 or 40.

It will be observed from Fig. 26 that when the shaft 36 is set in rotation directly from the shaft 5 through clutch 15, gear 13, and the intermediate associated gears, in the manner heretofore referred to, the direction of rotation of shaft 36, as shown by the arrow in Fig. 26, is opposite to the direction of rotation imparted to the shaft 28 when that shaft is set in rotation from shaft 5 in the manner heretofore referred to, and that this direction of rotation of the shaft 36, although opposite to the direction of rotation of the shaft 28, is in the same direction of rotation as that which is imparted to the shaft 36 from the shaft 28 through the gears in the gear frame 49 in the manner heretofore stated.

If now it be assumed that both the clutches 15 and 20 are in engagement with their cooperating gears, then a slow rotation would be imparted to shaft 28, while at the same time a more rapid rotation would be imparted to shaft 36. In this condition the greater torque exerted upon the gear frame 49 would come from the more rapidly rotating shaft 36, and as that shaft is turning in a direction opposite to that of shaft 28, that torque would have a tendency to turn gear frame 49 in a direction opposite to that impelled by the torque from shaft 28; in other words, in a direction permitting the teeth of lock wheel 51 to ride under the pawl 50 (shown in Fig. 27), thus permitting shaft 36 and shaft 28 to rotate simultaneously and at different speeds, the gear frame 49 simply following the direction of the greater speed, and, therefore, constituting a differential speed transmission. It is also, of course, obvious that when the shafts 36 and 28 are both thus set in rotation from shaft 5, the rotation transmitted to the shaft 53 will be that of the greater speed. It is also obvious that this rotation at the greater speed can at once be changed to rotation at the slower speed by simply disengaging the clutch 15 and by thereby discontinuing the direct drive to shaft 36, when the rotation of shaft 36 will drop in speed to the slow rotation imparted thereto by the shaft 28. It is also obvious that an intermittent speed of rotation from slow to fast or fast to slow can at any time be transmitted to shaft 53 by maintaining the driving connection to shaft 28 and by connecting or disconnecting the direct drive to shaft 36 for fast rotation. It is also obvious that rotation at either of these speeds can be

reversed in direction by shifting the clutch 43, and rotation of shaft 53 can be stopped altogether by disconnecting the clutch 20 if the shaft 28 is alone being driven or the clutch 15 if the shaft 36 is alone being directly driven, or both if both are being directly driven.

Change gears in slow and fast drive

The speed of the "slow" or "feed" movement and the speed of the "fast" traverse or return movement may be varied by means of the change gears 24, 25, 26, 27, and 32, 33, 34 and 35, respectively; the variation of speed for the slow movement being to meet the various conditions under which the cutting tool has to work, and the variation of speed for the fast movement being for reasons which will later be explained. It should be observed, however, that to render the differential mechanism referred to operative, that is, for the frame 49 to be locked against movement when the drive imparted is the slow rotation of shaft 28 and to be unlocked to follow the faster rotation of shaft 36 when that shaft is being directly driven, the fastest "slow" movement of shaft 28 should be slower than the slowest "fast" movement of shaft 36.

Proceeding now to the description of the transmission mechanism whereby the various rotations imparted to the single shaft 53 are transmitted for the reciprocating movement of the slide 60 or for the circular milling movement of the rotatable table 61, and of the manual or automatic operation of the clutches 15, 20 and 43, it may first be stated that the slide 60 is mounted for reciprocating movement upon the frame or housing 1, and that the table 61 is rotatably mounted upon the slide (Figs. 3, 4, and 28).

Immediate driving mechanism for the reciprocating slide

In a lug depending from the slide 60 (Fig. 4) is a nut 62, through which passes the feed screw 63 (Figs. 3, 4 and 27), the latter being journaled at one end in bushing 64 (Figs. 12 and 27) which is fixed in the housing 1, and which bushing secures the screw against an axial movement, the screw being journaled at its opposite end in the housing 1 itself (Figs. 3 and 27).

Mounted loose on bushing 64 (Figs. 12 and 27) is a gear 65, which is provided with clutch teeth 66. 67 is a cooperating toothed clutch turning with and sliding on the feed screw 63. Gear 65 meshes with the gear 68 on shaft 53 (Figs. 3 and 26), which gear 68 is formed as one-half of a spring shock absorber, the other half, 69, of which is provided with clutch teeth 70 and is mounted loose on bushing 54 in which shaft 53 is journaled. A toothed clutch 71 turns with and slides on shaft 53, and when engaged to clutch member 69, transmits motion from the shaft 53 over the gears 68 and 65 and clutch 67 to the feed

screw 63, which by rotation in the nut 62 attached to the reciprocating slide, moves this slide; and as shaft 53 may be rotated fast or slow, or intermittently fast and slow, in the manner heretofore stated, as fast or slow or intermittently fast and slow movement in either direction is imparted to the reciprocating slide.

10 *The rotatable work table and its immediate driving mechanism*

15 The reciprocating slide 60 is provided on its upper surface with an annular bearing (Figs. 3, 4, 28 and 29) to receive the circular table support 72, the latter being held in its bearing seat by the gib-plate 58, which is adjustable by the nut 59. To this support is secured the circular table 61, to which all work is fastened.

20 The circular table support 72 is provided with exterior peripheral gear teeth 73 (Figs. 3, 4, 15, 16, 28 and 29), in which meshes the worm 74 (see particularly Fig. 29), which worm is fixed on shaft 75, which shaft is 25 journaled in a bracket 76, which bracket, in turn, is journaled in slide 60, as shown in Fig. 3. On the end of shaft 75 and secured to it is a bevelled gear 77, which meshes with bevelled gear 78 on the shaft 79 (Figs. 3, 28 and 29), 30 which shaft 79 is also journaled in the bracket 76, the shaft 79 forming a fulcrum for the bracket in slide 60, as shown in Fig. 29, to permit the engagement or disengagement of worm 74 with the worm gear teeth 73 at will.

35 On the other end of shaft 79 is a bevelled gear 80 (Figs. 3 and 28) meshing with a bevelled gear 81 on shaft 82 which is journaled in slide 60. The shaft 82 carries fixed to it a spur gear 83, which meshes with the 40 spur gear 84 (Figs. 3 and 27), which is fixed on sleeve 85, which sleeve is journaled in the feed screw nut 62 depending from the reciprocating slide 60, and which sleeve 85 and spur gear 84, therefore, travel along with the 45 reciprocating slide. Through the sleeve 85, which is provided with a key, passes the splined shaft 86, which is journaled in bearings 87 and 88 of the housing 1.

50 The protruding end of shaft 86 carries a double toothed clutch 158 (Figs. 3 and 27) with teeth 89 and 90, respectively, rotating with the shaft and slideable thereon. Clutch teeth 89 may be engaged with the clutch teeth 91 on spur gear 92, the extending shaft end of this gear being journaled in housing 1, as shown in Figs. 3 and 27.

55 Gear 92 meshes with the gear 65, which, as stated, in turn meshes with the gear 68 on shaft 53 (Figs. 3, 26 and 27), and it is obvious that the same slow or fast, or intermittently slow and fast movement in either direction which has been imparted to shaft 53 will be imparted therefrom through the gears 68, 65 and 92 to the circular table 61 when the clutch

teeth 89 are engaged with the clutch teeth 91 of the spur gear 92.

60 *Automatic timing of the slow, fast, or intermittent movement of the circular work table*

70

The fast, slow or intermittently fast and slow movements of the straight reciprocating slide or of the circular work table should, of course, be timed to meet the different conditions of the work, and, therefore, adjustable dogs are provided which travel along with the reciprocating slide and the work table, respectively, and on their path operate through intermediate members upon the clutches for the slow and fast drives and for the reversal of the direction of the drives.

75

Considering first the continuous circular movement of the work table 61 at a slow or cutting feed, work fastened to the table will be passed under the cutter, and after being cut will be removed and replaced by an unfinished work piece. Work pieces milled by this method require in most instances special holding fixtures which will be arranged in circular form, and the most efficient arrangement of the work pieces would be to arrange them so closely adjacent in a circular path that the cutting action is a continuous one, that is, that the cutter starts cutting the next work piece before it has entirely left the piece last acted upon. This, however, depends greatly on the shape of the work pieces and the means by which they can be held in place upon the work table. Means for holding the work pieces, that is, the fixtures for holding them, must be provided to form a full circle, for continuous circular milling, and this, because of the expense of the numerous holding fixtures, is only warranted when milling parts in large quantities. For smaller quantities, one, two or three fixtures may be placed upon the work table, or any number of fixtures warranted by the quantities to be milled, and by means of the driving movements heretofore 100 explained, the space between these fixtures can be rapidly traversed by the cutter by a rapid rotative movement of the table. This method will also be employed whenever the work pieces are of such a shape as not to permit their close setting to each other.

80

90

95

100

105

110

115

Hand operation of slow feed clutch

The slow feed movement for cutting will be started by means of a hand lever 93 (Figs. 1, 5, 6 and 7), which is fixed to pinion 94, plunger rack 95, pinion 96 rotatable on the stud 97, the eccentric pin 98 thereon, and the clutch shoe 99, which is operated by the eccentric pin and which enters the circular groove of the clutch 20.

120

125

Automatic timing of rapid feed movement

For the quick traverse movement, dogs 100 and 101 (Figs. 1, 5 and 9) are provided, of

130

which there may be adjustably attached to the rotatable work table 61 as many as are desired to change the speed from a slow to a fast movement and vice versa. In the path of the dogs are plungers 102 and 103 in slide 60 (see particularly Fig. 5), both of which are provided with rack teeth, and in mesh with the pinion 104. The shaft of this pinion (see particularly Fig. 9) is provided on the end opposite the pinion, with gear teeth which transmit movement over the intermediate gear segment 105 (see Fig. 10) to the pinion 106 on shaft 107 (Fig. 9). The shaft 107 is splined and is designed to slide with the reciprocation of the slide 60 through the keyed pinion lever 108 (Figs. 5 and 9), which is held axially by the members 109 and 110 (Fig. 9), but which is free to rock around its center by any rocking movement imparted to shaft 107.

Connected to the pinion lever 108 is the clutch throw rod 111 (Figs. 5 and 26), the other end of which throw rod is connected to the forked lever 112, which forked lever is mounted to freely rock upon shaft 113, which shaft is secured in the main feed box 10 and in the bracket 56. The clutch shifter lever 114 is also mounted to freely rock upon the shaft 113 and is provided upon its lower depending arm with the shoes 115 which enter the grooves 116 in the clutch 15. This clutch shifting lever has an arm 122 upwardly extending between adjustable stop screws 117 and 118 of the lever 112. This lever 112 is U-shaped in plan view, as shown in Fig. 26, the adjustable stop screws 117 and 118 being extended through the free extremities of the U-shaped arm, as shown in Fig. 26, and the throw rod 111 being connected to the center of the U-shaped arm, as shown in Fig. 26. In side elevation, as shown in Fig. 5, the lever 112 is right-angled, having an arm 119 provided at its extremity with a roll 120, which is in contact with the bevelled spring plunger 121.

Assuming now that clutch 15 is held in the "out" position by the spring plunger 121, as shown in Fig. 5, and assuming the slow speed clutch 20 engaged and the work table therefore rotating at a slow or feed rate, to start the quick traverse movement of the table, dog 100, carried around in a circular path upon the table, will strike with its bevelled end the similarly bevelled end of the plunger 102, and will press that plunger down, thus imparting an oscillating movement to the clutch throw rod 111 through the oscillation of the pinion lever 108 in the manner heretofore described, the clutch throw rod 111 oscillating the lever 112. The lever 112 will therefore rock around its center upon the shaft 113, but its movement will not affect the lever 114 until the screw 117 comes in contact with the end 122 of the lever 114, at which time the upper end of lever 114 is moved to the right

(as viewed in Fig. 5), and the lower end is moved to the left, moving clutch 15 toward engagement with the teeth 14 of the gear 13. In the meantime roller 120 upon the laterally extending arm on lever 112 rocks downwardly and across the bevelled end of plunger 122 pushing back this plunger, which plunger, after the roller has passed its highest point, will move forwardly, or toward the left, as viewed in Fig. 5, under the impulse of its spring, and throw the clutch 15 instantaneously into full engagement, thus starting the "fast" movement.

In a similar way, by opposite direction of movement of the clutch throw rod 111 and the cooperating levers heretofore referred to, the clutch 15 will be disengaged, which is accomplished by dog 101. Dog 101 travelling now with the "fast" rotary movement of the table, will in its path of movement strike the plunger 103 and press it down, thus imparting movement to the lever 112 in the direction opposite to that heretofore referred to. This movement will not affect lever 114 until the screw 118 comes in contact with the end 122 of the lever 114. Roller 120 again pushes back the plunger 121 and after passing the highest point of the plunger, the latter will push forward and throw the clutch out of engagement, thus returning the parts to the "slow" movement again, it being understood that the slow clutch 20 is still in engagement.

Automatic timing of the slow and fast movement of the reciprocatory slide

Considering now the milling of work requiring a straight-line movement, which is accomplished by locking the circular table 61 to the straight slide 60, in the manner herein-after described, and by taking the drive from shaft 53 over the clutch 71 and gear 68 thereon (Fig. 26) and over gear 65 cooperating with gear 68 (Fig. 27) and clutch 67 to the feed screw 63, instead of over the gear 92 and clutch teeth 91 and 89 to the shaft 86 as was required for the circular movement of table 61, it is quite obvious that all motions, "slow" and "fast", and intermittently slow and fast, are now imparted to the reciprocatory slide 60. For the starting and stopping of such motions, the adjustable dogs 123 and 124 (Figs. 1, 5 and 9) are provided upon the reciprocatory slide, of which adjustable dogs there may be as many as desired to change the movement from a slow to fast movement, or vice versa.

These dogs, in their straight-line travel, strike with their bevelled ends the like bevelled ends of the plungers 125 and 126, respectively, which plungers are mounted for upward and downward sliding movement in a plug 110 (Fig. 5) in the housing 10. Both of these plungers are provided with rack teeth (Figs. 5 and 7), which are in mesh with

the pinion lever 108 heretofore referred to, and which plungers when pressed downwardly, will therefore operate the clutch 15 in exactly the same manner as has been heretofore described for the circular milling movements.

During this variation from "slow" to "fast" and return to "slow" driving movement, it is, of course, understood that clutch 20 for the slow movement of the slide is engaged with the worm wheel 17 (Fig. 26) by means of the clutch shoe 99 manually operated in the manner heretofore stated by the lever 93 (Fig. 5). Means is provided for automatically disengaging the slow movement of the reciprocatory slide, which, it must also be understood, would be a disengagement of the slow movement of the rotating work table if that were in operation. Such means comprises the adjustable dog 127 (Figs. 1, 5 and 6) on the reciprocatory slide 60, which dog travels along in a straight path with the slide, and on its path strikes the plunger 95, presses it down, and which plunger, as shown particularly in Fig. 6, upon its downward movement, by rack teeth thereon cooperating with teeth upon the pinion 96, rotates that pinion in a direction to move the eccentric pin 98 to shift the clutch shoe 99 (Fig. 5) to disengaging position of the clutch 20 (Fig. 26).

Automatic means for controlling the direction of movement of the reciprocatory slide and rotatable table

The direction of movement of the slide or table is controlled by the position of clutch 43 (Figs. 4 and 26) in engagement with either bevelled gears 39 or 40, and such engagement is affected by the operation of hand lever 128 (Figs. 1 and 9) which with its connecting parts 129, 130, 131, 132, 133, 134, 135, 136, 137 and 137a (Figs. 9, 26 and 30) constitute a clutch shifting mechanism similar to the one described for the shifting of clutch 15 for the engagement of the fast drive. A hand operation of lever 128 will therefore shift clutch 43 (Figs. 4 and 26) alternately in opposite directions to change the direction of rotation imparted to shaft 53.

For the automatic shifting of the clutch 43, there is connected to the lever 128 a shaft 138 (Figs. 1 and 9) sliding in stationary member 110 (as shown particularly in Fig. 9), said shaft being in the path of travel of two adjustable dogs 139 and 140 (Fig. 1), which are mounted on the slide 60. It is obvious that when the slide 60 is travelling in a straight path, in the plane of the drawing of Fig. 1, the dogs 139 and 140 will alternately come in engagement with opposite ends of the shaft 138 and will axially shift the same, which will accomplish the same function of shifting the clutch 43 as may be accomplished by operation of the hand lever 128, in the manner heretofore described.

Various cycles of movement obtained by setting the adjustable dogs

Various cycles of movement may be obtained by setting the dogs to various positions on the table, some of which movements, for example, are as follows:—

A continuous slow movement of the reciprocatory slide back and forth may be obtained by engaging clutch 20 and operating clutch 43 by the dogs 139 and 140; 75

A continuous fast movement back and forth of the reciprocatory slide may be obtained by engaging clutch 15 and operating clutch 43 by the dogs 139 and 140; 80

A slow feed across the work may be obtained by engaging clutch 20, affecting a reverse by either dog 139 or 140, and feeding back slowly to the starting position so as to refinish the work, and then stopping the slow drive by dog 127, disengaging clutch 20 (Figs. 5 and 6); or 85

Clutch 15 may be manually engaged (in the manner hereinafter to be described), starting the fast drive, the work approaching the cutter quickly, then stopping the fast drive by the dog 124 (Fig. 5), disengaging the clutch 15, through the medium of the plunger 126, pinion 108, throw rod 111, and levers 112 and 114, then starting the slow movement by manually engaging clutch 20 by lever 93 (Fig. 5), so as to take a cut across the work, then speed up again by dog 123 moving clutch 15 to engaging position by means of the engagement of dog 123 with plunger 125 and the various cooperating parts (Fig. 5), to provide a fast traverse to move the next work piece upon the table to the cutter, then slow down again for cutting by disengaging the clutch 15 by a dog 124 in the manner heretofore described, and so on, 90

and repeating the operation of clutch 15 by dogs 123 and 124 as often as desired, until all the work pieces have passed the cutter, and then effecting a reverse of the slide by either dog 139 or 140 (Figs. 1 and 9), and repeating the intermittent movement on the backward stroke by dogs 141 and 142 (Fig. 9) mounted on the slide 60 and identical in structure and function with the dogs 123 and 124, so as to refinish the work at a slow rate of speed and traversing quickly to bring the work pieces successively beneath the cutter; or 105

The slide may be returned completely to initial position without the interruption and finally stopped at the starting position by dog 124 (Fig. 5) disengaging the clutch 15, and dog 127 disengaging the clutch 20. 110

The work may now be removed and new work set and the cycle may be repeated. 115

Or the movement of the slide may be stopped after the cut has been taken at the end of the slow forward stroke, by dog 127 (Figs. 1, 5 and 6), then the work may be re- 120

5 moved so as not to mar it on the backward stroke, and after its removal the fast movement of the slide may be started by manually operating clutch 15. The direction of movement, still forward, will immediately be reversed by either dog 139 or 140 (Figs. 1 and 7), the fast return movement to be finally stopped by dog 124 disengaging clutch 15 (Fig. 5). New work may now be set and the 10 cycle repeated.

10 Dogs 123 and 124, 141 and 142 (as shown in Figs. 1 and 9) are provided with pivoted latches 143 so that they do not interfere on the respective return strokes of the slide with 15 the clutch operating plungers 125 and 126.

15 From the foregoing it will be seen that almost any desired movement may be derived with respect to changing from a slow to a fast movement at either the forward or re- 20 turn stroke of the slide.

25 Since the same slow or fast movement in either direction may also be transmitted to the rotatable work table mounted upon the slide, it follows that by a like arrangement 25 of adjustable dogs upon the work table, a like variety of slow and fast movements may be transmitted to the table in either direction of rotation of the same for circular milling.

30 *Combination of straight milling with an indexing movement of the table*

35 The above described method of straight milling by reciprocation of the slide, while highly efficient, is preferably employed how- 35 ever only where the pieces to be milled are of such size or weight, or otherwise of a nature, that the placing of work pieces on the table is either limited to one or, where a plurality of work pieces is placed on the table, permits 40 only of setting in one row to the exclusion of other work pieces, or where the pieces to be milled are very few and held on the work table by a single work holding fixture. In all other cases I preferably fasten the pieces 45 to the circular table 61 to one side of the center of the table, and while cutting is being done upon these, work will be fastened to the table symmetrically on the opposite side of the center of the table, so as to be positioned 50 in a path beneath the cutters when the table is indexed the required number of divisions, in the manner already outlined. It is ob- 55 vious that this method of milling saves considerable time as the setting of new work and the removing of the finished work is being done while the cutter is working upon other work being fed beneath the cutter. All the different movements of the slide men- 60 tioned before, that is, slow, fast, and inter- 65 mittently slow and fast, both in advance and reverse, with their variations, may, of course, be employed, with the addition that at the end of the return stroke, the indexing move- 70 ment of the table 61 takes place.

65 The table is normally power driven but

may be manually driven in a manner later to be described. The power driving mechanism may be engaged in operation manually by the operation of the hand lever 144 (Figs. 1, 20, 21 and 22) in a manner also later to be 70 described, or automatically by the engagement of the power drive by the action of an adjustable dog 145 (Figs. 4, 17 and 31) through the movement of the slide.

75 *Drive for indexing movement of the work table*

The power drive for the indexing movement of the work table is taken off the main feed shaft 5 and transmitted over clutch 154 (Figs. 5 and 26), worm 146, which is loose on shaft 5 (Fig. 3) and which may be engaged with clutch 154 as shown in Fig. 5, worm wheel 147 (Figs. 5 and 27) and the intermediate shafts and gears 148, 149, 150, 151, and 152 (Figs. 3, 26 and 27) to the spur gear 153, which is loose on shaft 86. Clutch 154 (Figs. 5 and 26), which turns with and slides on shaft 5, may be brought in mesh with the clutch teeth on worm 146 by means of the clutch shoe 155 (Fig. 5) and the shifter rod 156, whenever the motion of the indexing drive parts is desired, and may be kept disengaged at other times. Spur gear 153 (Figs. 3 and 27) is provided with clutch teeth 157. 95 with which the clutch 90 of the teeth 158 can be brought into mesh, and thus the motion from the gear 153 be transmitted to the shaft 86, from which in turn movement is taken over the gears 84 and 83 (Figs. 3, 27 and 28) 100 to the shaft 82.

It should be recalled that shaft 86, gears 84 and 83 and shaft 82 are also used for the transmission of motion for the circular drive of the table 61 when the latter is used for the continuous circular milling, the movement then being derived by engaging the clutch teeth 89 (Fig. 27) of clutch 158 to the clutch teeth 91 of spur gear 92, to receive the benefit of the speed changes as derived from the 110 shaft 53, in the manner heretofore stated. It should also be observed that the rotation of shaft 86 and shaft 82 as derived from the spur gear 153 is a constant one, as the indexing movement of the table should, for practical 115 reasons, be a constant one.

A view of the driving mechanisms, particularly as shown in plan in Fig. 26, will make clear the lines of transmission of the drives from main driving shaft 5 to the reciprocating slide and the rotatable work table thereon. A slow driving movement is transmitted from shaft 5 to shaft 53 from the right-hand end of shaft 5, as viewed in Fig. 26, through the worm 16, worm wheel 17, 120 clutch 20, gears 21, 22, 24, 25, 26 and 27, shaft 28, the differential mechanism in frame 49, shaft 38, and the reversing mechanism 39 40 and 43 to the shaft 53, while a fast movement 125 is transmitted from the left-hand portion of 130

shaft 5, as viewed in Fig. 26, directly through clutch 15, gears 13, 29, 30, 32, 33, 34 and 35, shaft 36, and the reversing mechanism to shaft 53, and the constant speed indexing movement is taken from an intermediate portion of shaft 5, as viewed in Fig. 26, through the worm 146, clutch 154 and gear 147 (Fig. 27). The two speed movements referred to as transmitted through shaft 53, are then transmitted to the slide and the work table through the shafts 63 and 86, respectively, and the cooperating clutches and gears shown at the left-hand end of these shafts, as viewed in Fig. 27, while the constant speed movement referred to is taken from shaft 5 to shaft 86 through worm 146, gear 147, shaft 148, gears 149 and 150, shaft 151, gear 152, and gear 153.

Continuing with the detailed description of the indexing drive, fixed to shaft 82 is a bevelled gear 159 in mesh with bevelled gear 160 on shaft 161 (Figs. 3, 15, 27 and 28). Shaft 161 is journaled in bracket 162, which bracket is fastened to the slide 60, as shown particularly in Fig. 3. Indexing drive pinion 163, turning with and sliding on shaft 161, is provided with clutch teeth 164, which may be brought into mesh with clutch teeth 165 of the pilot gear 166, which is mounted loose on shaft 161, but in mesh with the internal gear 167. The latter is secured to the circular table support 72, which in turn carries the work table 61 (Figs. 3, 15, 16, 17 and 18). By this arrangement of parts, whenever the clutch teeth of the gears 163 and 166 are brought into mesh, the indexing motion is transmitted to the table.

Means for locking the work table against rotary movement upon the slide and for releasing the same for such movement

As stated before, it is to be understood that when the reciprocating slide is being driven in straight-line milling, the rotatable work table is locked to the slide against rotation, and to rotate the table either for circular milling or for partial rotation for indexing, the table must be unlocked from the slide. Moreover, after indexing a certain division or the required number of divisions, the indexing drive must be stopped and the table again locked to the slide.

Assuming the slide 60 in movement, and the engagement of the indexing drive actuated as heretofore stated by the clutch rod 156 engaging the clutch 155 with the worm 146 (Fig. 5), the table lock pin 168 (Figs. 4, 17 and 31) is withdrawn by the downward movement of the lock pin operating lever 169 (Fig. 17) caused by engagement therewith of the dog 145, which is adjustable upon the frame of the machine adjacent the slide 60. This lever 169 is fulcrumed at 170 and connected by link 171 to the lever 172, which while travelling along with the slide 60, en-

counters on its path and inclined face 175 (Fig. 17) of the dog 145, along which inclined face the roll 174 travels downwardly, thus withdrawing the table lock pin against the pressure of its spring 188.

Lever 169 has an upwardly extending arm 169' (Figs. 16 and 17) in mesh with a pinion 177 (Fig. 20), on shaft 178, which shaft also carries the pinion 179, which is in mesh with the rack 176 (Figs. 16, 17 and 20), and whereby upward and downward movement is transmitted to the rack 176 from the lever 169. The rack 176 is designed to cause the engagement of the index drive pinion 163 with the pilot gear 166.

The upper portion of the rack 176 above the teeth thereon is cylindrical, as shown in Figs. 16 and 17, and this upper portion is surrounded by the tubular part of a forked member 182, the fork of which extends in a grooved portion of the gear pinion 163, as shown in Figs. 15 and 16. The tubular portion of the forked member in its upper part presents a close sliding fit about the tubular portion of the rack 176 and its lower part is recessed for the reception of a spring 180 which abuts below upon a collar on the tubular portion of the rack 176 and above against that portion of the tubular part of the forked member which has a sliding fit upon the rack 176, all as shown particularly in Fig. 15.

The forked member is normally held in its lowermost position and with the gear pinion 163 in its lowermost position out of engagement with the pilot gear 166, as shown in Figs. 15 and 16, by a spring-pressed latch 181, whose nose extends through a vertical slot in the tubular bearing of the forked member to hold that forked member in its lowermost position, as shown in Fig. 16.

The upward movement of the rack 176, while compressing the spring 180, continues to a point where it releases by means of a pin 183 extending through the upper cylindrical portion of the rack, the spring-pressed latch 181, as shown in Fig. 17, and which latch until thus released has held the fork 182 in its lowermost position, as shown in Fig. 16. As soon as this fork is thus released, the energy of the compressed spring 180 throws the fork with the index drive pinion 163 upwardly, bringing the clutch teeth of the index drive pinion into mesh with the clutch teeth of the pilot gear 166.

The internal gear of the rotatable work table is a wide-faced gear, having a width of face equal to the face of the pilot gear, plus the face of the drive pinion, plus the depth of the clutch teeth of both of these elements.

Upon the face of the internal gear at equally spaced distances corresponding to the number of degrees for indexing are cut-out portions, as shown in Fig. 18, the number of cut-out portions corresponding to the

number of divisions of the indexing movements to be given to the rotatable table. The width of the cut-out portion, measuring across the face of the gear, is such as to always leave above the smooth portion a sufficient width of gear teeth to engage the pilot gear, as shown in Fig. 18, and the drive pinion is designed to be moved upwardly into initial engagement and downwardly away from such engagement with the pilot gear only across a cut-out portion of the internal gear.

Bringing the clutch teeth of the drive pinion into mesh with the clutch teeth of the pilot gears starts the indexing movement of the table, the initial rotation being transmitted to the table from the drive pinion through the pilot gear, since that gear is the only one in mesh with the teeth of the internal gear of the table across a cut-out portion, and until the full-faced teeth of the internal gear are reached by the drive pinion. After the full-faced toothed portion of the internal gear is reached, it is necessary to separate the drive pinion from the pilot gear, as otherwise when the next cut-out portion of the internal gear of the rotatable table is reached, that table would continue to be rotated through the intermeshing of the pilot gear and the drive pinion, instead of coming to a stop as is desired and is designed by the cut-out portion. When, therefore, after the initial rotation through the pilot gear has started, and the drive pinion separated from the pilot gear, the drive pinion continues along the full-faced toothed portion of the internal gear to rotate the table until a cut-out portion is again reached when the drive pinion becomes inoperative. It is obvious that this driving position of the driving pinion, separated from the pilot gear, is an intermediate position of the drive pinion, that is, not its lowermost position, as shown in Figs. 15 and 16, for the lowermost position of the drive pinion is one entirely below the internal gear. This intermediate position of the driving pinion, in operative position to drive the rotatable table, and yet not in engagement with the pilot gear, is shown in Fig. 18. We have, therefore, three positions of the drive pinion and the internal gear; the first being the lowermost position of the drive pinion before the indexing drive is begun at all, as shown in Figs. 15 and 16, the second being the highermost position of the drive pinion in engagement with the pilot gear to start the rotation of the table, as shown in Fig. 17, and the third being the intermediate position of the drive pinion to directly drive the table until a cut-out portion of the internal gear is reached, as shown in Fig. 18.

The driving pinion, being in the intermediate position last referred to and directly driving the work table in rotative move-

ment, will run out of mesh upon a cut-out portion of the internal gear of that table, and the table will stop, and in which position the table lock pin 168 will be just opposite a lock pin bushing 184 in the table, there being as many lock pin bushings in the table as cut-out portions on the internal gear of the table and similarly distributed.

During the indexing movement of the table the lock pin must be held down in unlocking position, and should be released for upward movement into locking position as soon as the table movement is stopped. This is accomplished in the following manner: When through the downward movement of the lock pin the rack 176 moves up to its highest position, plunger 185, mounted for axial sliding movement in bracket 162 and impelled forward or toward the left (as shown in Fig. 14) by spring 187, enters a notch 186 (Fig. 17) in the rack 176, thus locking the rack in its highest position and the lock pin 168 in its lowest position.

It must be borne in mind that the lock pin spring 188 (Fig. 17) is in a compressed state in the lowermost position of the lock pin, and is held in this state as long as the roll 174 is held in its lowest position by the dog 145. However, slide 60, during the process of indexing the rotatable table, keeps on travelling (when the indexing and return movements of the reciprocating slide are performed simultaneously), and the travel will continue for a distance sufficient to bring the shaft away from the dog 145, and to permit the shaft to move up with the lock pin after the indexing has been performed. After this, the motion of the slide can be stopped at any desired point. While the shaft is moving away from the dog, however, the lock pin 168 would be moved up again prematurely by the spring 188, if not otherwise held down during the continuation of the indexing. As before stated, however, the rack 176 and lock pin 168 are held down by the plunger 185 engaging the notch 186 in the rack.

As soon as the index drive pinion runs out of mesh with the internal gear, that is, the drive pinion runs upon a cut-out portion of the face of the internal gear, and when the lock pin 168 is just opposite a bushing 184, plunger 185 must be withdrawn to release the rack 176 and the lock pin 168, and this is automatically accomplished by the cam 189 (Figs. 14 and 18), which is mounted to the continuously rotating shaft 161.

The action of this cam in releasing the lock pin is as follows: Plunger 185, which is free to slide in the bracket 162, is provided with the stud 190 (Figs. 14 and 17), which stud enters the arcuate formed groove 191 of the arm 192 (Fig. 14). This arm is fulcrumed at one end at 193 to the rotatable table support bearing the internal gear, as shown in Fig.

14, and hence is carried around in a circular path in the rotation of the table.

Spring 187, as shown in Fig. 14, impels the arm 192 toward the center of the internal gear, the movement being limited by screw 194 in the arm 192 and the slot 195 in the arm support 196.

Assuming now the lock pin 168 in a position locking the table, that is, in its uppermost position in bushing 184 (Figs. 4 and 31) and, therefore, the rack 176 down and plunger 185 pressed against the cylindrical portion of the rack above the notch 186, and the stud 190 on the plunger 185 in the arcuate slot 191 of the arm 192 (Fig. 14), the free end of arm 192 will just be in a position to clear the outside diameter of the rotating cam 189, as shown in Fig. 14. As soon as the table lock pin is withdrawn in the manner heretofore stated, and the indexing drive engaged, the rack at the time having moved upwardly, spring 187 will throw arm 192 and plunger 185 forwardly, or to the left, as viewed in Fig. 14; the plunger will enter the notch 186, as shown in Fig. 17, the table lock pin will be held in the down or unlocking position, and the free end of arm 192 will enter the toothed space of the cam, as shown in Fig. 14. The indexing movement having begun, the cam 189 and arm 192 are both travelling at the same circumferential speed, with the arm moving away from the cam and the arcuate groove 191 retreating from the stud 190.

Arm 192 is cut out at 197 (Fig. 14) so as not to interfere with the tooth of the cam.

There may be as many arms 192 mounted upon the internal gear 167 as are desired to make indexing divisions, and it is obvious that when the next arm comes around, stud 190 will enter the groove 191 and arm 192 enter the toothed space of cam 189; and after coming to a stop, that is, when the index drive pinion runs out of mesh with the internal gear, the tooth of the revolving cam 189 will push the free end of arm 192 back, that is, toward the right in Fig. 14, and the stud 190, being in the slot 191, is carried back, that is, toward the right as viewed in Fig. 14, taking along the plunger 185, and thus releasing the plunger from the notch 186 in rack 176 (Fig. 17), and thus releasing the rack for downward movement, and the lock pin 168, which through the energy of the compressed spring, will be thrown upwardly into bushing 184 and lock the table.

As has been before stated, after the pilot gear 166 has guided the drive pinion into mesh with the internal gear 167, by the clutch teeth 164 of the index drive pinion being brought into mesh with the clutch teeth 165 of the pilot gear 166, so as to start the indexing movement of the table, the clutch teeth should be separated, that is, the drive pinion should be pushed downwardly to its intermediate position so that it alone will do the

driving of the table and the table will come to a stop whenever this drive pinion runs out of mesh with the internal gear at one of the cut-out places on the face of that gear. This separation of the drive pinion from the pilot gear and the maintaining of the drive pinion in intermediate driving position is accomplished by the following mechanism: To the same bracket 162 in the slide 60 in which is journaled the shaft of the driving and pilot gears, is pivoted at the top, as shown in Fig. 18, a finger 201, designed in its position as shown in Fig. 18 to press downwardly upon a plunger 202 normally impelled upwardly by spring 207, the lower end of which plunger bears upon the forked member 182 already referred to. Finger 201 bears a shaft 200 designed to be engaged by a double dog 199 upon the extremity of an arm 198 attached to the ring support 72 of the internal gear 167, as shown in Fig. 14, when that dog is moved in a circular path by the rotation of the table over the shaft 200 of the finger 201.

Assuming now that the pilot gear has just guided the index drive gear into full mesh with the internal gear 167, the arm 198 with the bevelled dog 199 thereon (Figs. 14 and 18) is travelling along with the internal gear, and approaches the shaft 200 of the finger 201, and presses it down, thus also pressing down the spring-pressed plunger 202 and the fork 182, which carries down the drive pinion 163 to its intermediate position separating its clutch teeth from the clutch teeth of the pilot gear and yet maintains the drive pinion in engagement with the lower portion of the teeth of the internal gear, all as shown in Fig. 18.

It is essential to hold driving pinion 163 in this intermediate position by means of the finger 201 in the position shown in Fig. 18, during the entire time of the indexing movement, as otherwise spring 180 surrounding the rack 176, which is still under partial compression, would throw the clutch teeth of the index drive pinion back into mesh again with the clutch teeth of the pilot gear, as soon as the dog 199 had passed the shaft 200, thus permitting the finger 201 to pivot upwardly and release the plunger 202 and the fork 182 for upward movement, which re-engagement of the driving pinion with the pilot gear would prevent the stopping of the table at the completion of the indexing movement.

Finger 201 is thus held down after the dog 199 has passed the shaft 200 (Fig. 18) by the latch 203 (Fig. 19) which is pivoted at 204 to bracket 162 and which snaps over the end of the finger by the pressure of the spring 205.

It is equally essential that after the drive pinion has been held down in its intermediate but driving position with the work table during the indexing movement, as shown in Fig. 18, and as soon as the drive pinion runs

into a cut-out portion of the internal gear so that the indexing movement comes to a stop, all the parts be restored to their initial position for the beginning of another indexing movement when desired. It is further to be observed that for the beginning of another indexing movement, the drive pinion must again come into complete engagement with the pilot gear, which engagement is impossible if the finger 201 be not released from the position, as shown in Fig. 18, in which it was maintained during the last indexing. In restoring the parts to their original position for the beginning of another indexing movement, means must therefore be provided for releasing the finger 201 and thereby releasing the plunger 202 from the position shown in Fig. 18, so that the fork 182 can carry the drive pinion 163 upward into complete engagement with the pilot gear 166.

This release of the finger 201 is accomplished by a pin 206 mounted in the end of the rack 176 (Fig. 15 and Fig. 19), which pin upon the downward movement of the rack 176 in the restoration of the parts to their initial position, trips the latch 203 (Fig. 19) away from holding position upon the finger 201, thus permitting the finger 201 to pivot upwardly under the impulse of the spring-pressed plunger 202, the finger 201 remaining in the upward position until upon the next indexing movement the dog 199 comes into engagement with the shaft 200 on the finger 201, as shown in Fig. 18. Therefore, at the end of the indexing movement, when by the action of the cam 189 (Fig. 14) plunger 185 releases the rack 176 in the manner heretofore stated, and the rack moves downwardly and the lock pin 168 correspondingly upwardly to lock the table, the spring 180 surrounding the rack is released from pressure (Fig. 16), thus permitting the fork 182 to move downwardly, carrying the drive pinion 163 to its lowermost position, and in this downward movement of the rack 176, the pin 206 trips the latch 203 from the finger 201, the finger being impelled forwardly by the spring-pressed plunger 202, and all the parts are restored to their initial position, and ready for the next indexing movement.

Manual engagement of the index drive

In the heretofore described movement of the index drive, it is to be recalled that that drive is set in operation automatically by the dog 145 coming in contact with the shaft 174 on the depending members of the lever 169 (Fig. 17). The index drive may also be engaged manually by the operation of the hand lever 144 (Figs. 20, 21 and 22), by connecting the hand lever shaft 208 to the shaft 178 through the medium of a toothed clutch coupling, one-half 214 (Fig. 22) of which is

fixed to the shaft 178, and the other half, 215, of which is fixed to the shaft 208. Hand lever 144 is fulcrumed at 209 (Fig. 20) in the bushing 210 (Fig. 22), which bushing has its bearing in the bracket 211, the latter being fastened to the slide 60. The end of lever 144 is also connected to the shaft 208 by pin 212 (Figs. 20 and 22). The shaft 208 is splined and has a sliding bearing in the bushing 210 and is caused to turn with the bearing through the connection with the key 213 (Fig. 22). Normally, clutch coupling 214, 215, is held disengaged by the spring 216, and the hand lever 144 is not affected in any way when engaging the index drive automatically through the movement of the slide and the dog 145 as heretofore described.

When engaging the index driving mechanism by hand, hand lever 144, resting against pin 217 (Fig. 21) is first pulled out, so that the lever pivots upon its fulcrum 209 (Fig. 20), which pivoting moves the shaft 208 with the clutch 215 into engagement with the clutch 214. In this position, latch 218 (Figs. 20, 22 and 25) is impelled by pressure of the spring 219 to enter the annular groove 220 in the shaft 208, thus locking the shaft with the clutch parts 214 and 215 in engagement, against the pressure of the spring 216. Lever 144 is now swung over to contact the pin 221 (Fig. 21), which movement turns the shaft 208 and with it the shaft 178, thus rotating the pinion 179 and impelling the arm 169' of the lever 169 and the lock pin 168 downwardly, the lock pin being withdrawn from locking position with the table. This same movement of shaft 178 and the pinion 179 thereon impels the rack 176 upwardly until the latter is locked by the plunger 185 (Fig. 17), all in the manner as when operated automatically by the dog 145 through the movement of the slide.

At the moment of locking, the latch 218 (Fig. 25), which is hinged in bushing 210 and which, therefore, turns with the shaft, has approached the stationary stop screw 222 in the bracket 211, and is pushed out of the groove by engagement with said stop screw. The shaft 208 being, therefore, released from its locking position, is impelled by spring 216 outwardly or to the left, as viewed in Fig. 22, thus moving clutch 215 out of engagement with clutch 214, so that when the indexing movement stops and the table lock pin is impelled upwardly into locking position by its spring 188 (Figs. 16 and 17), no motion is transmitted to the hand lever, and thereby danger to the operator is avoided.

Complementary locking of the indexing and circular table driving mechanisms

In either milling operation, continuously circular, or straight milling with the indexing movement of the table, heretofore re-

ferred to, it is necessary to operate the table lock pin. It is, therefore, essential to unlock the mechanism in such a way that when the table lock pin is operated in connection with the continuous circular milling, it should lock the mechanism for the operation of the indexing drive, and vice versa.

It should be borne in mind that the indexing movement of the table is a constant one, and the movement for continuous milling a variable one, and the unlocking of the mechanisms should permit the engagement of either one or the other movement, but not both simultaneously, thus rendering the machine operative and safe independently of the carefulness of the operator.

Assuming the table lock pin in position locking the table and the table drive worm 74 (Figs. 16, 17 and 29) out of mesh with the worm wheel 72, 73, to now set the machine for circular milling, the lock pin must first be withdrawn, and as soon as it is clear of the table, the worm should be moved into mesh with the wormwheel in the position shown in Fig. 29. This is done in the following manner:

Bracket 76 with the worm wheel 74 is fulcrumed at 79, as already stated, and the worm is brought into mesh with the worm wheel 30 by turning the eccentric shaft 233 by means of the hand lever 224 (Figs. 1, 29 and 31), the eccentric entering the slot 225 in the bracket 76 (Fig. 29). Shaft 223 is provided on a portion extending beyond the slot 225 (as shown to the left thereof in Fig. 31), with gear teeth 226, which are in mesh with the rack 227 (Figs. 20 and 31). Turning the eccentric shaft 223 moves the rack forward, the bevelled end 228 (Fig. 16) of the rack 40 encountering on its path the stud 229 on the lever 169, pressing the latter down, and with it the locking pin, thus setting the table free for the circular driving movement. But, after pressing the lock pin down just sufficiently to clear the table, stud 229 is in position to enter the notch 230 of the rack 227, and the notch 230 moves further over the stud (to the left as viewed in Fig. 16) by the further turning of the eccentric shaft 223 to 50 bring the worm 74 into mesh with the teeth 73 of the external gear of the table (Fig. 29).

While the lock pin is moved down by the foregoing operation, rack 176 of necessity moves upward, but because of the restraint of further movement of lever 169 by reason of the stud 229 thereon entering the notch 230 of rack 227, the rack 176 is not moved so far upwardly as to release the fork 182 (Fig. 16) for the engagement of the indexing drive, 60 the movement of rack 176 having stopped before the pin 183 reaches the latch 181. Stud 229, now in notch 230, prevents any further movement of the lever 169, and renders the accidental engagement of the index drive impossible. Consequently, to engage the index

drive, stud 229 must be out of the notch 230, which also means the worm out of mesh with the wheel (Fig. 29), and only after this has been done can the lock pin be moved further down and the rack be moved further up, to cause pin 183 (Fig. 16) to push the latch outwardly and release the fork 182 for the engagement of the index drive. 70

From the foregoing it is obvious that when the worm 74 (Fig. 29) is operated to engage 75 the gear teeth 73 for the circular milling, the lock pin is unlocked from the table to set the table free for rotation in circular milling, but the index gear 163 is locked from moving upwardly into engagement with the internal gear 167, and the indexing movement of the table is prevented. 80

On the other hand, when the handle 224 and the worm 74 (Figs. 29 and 31) are in the "out" position, and hence the circular milling 85 drive disengaged, and when the indexing drive is engaged by engagement of the drive pinion 163 with the pilot gear 166, as shown in Fig. 17, stud 229 is in the path of the end 231 (Fig. 17) of the rack 227, and an attempt to throw the worm into mesh with the wheel in the position shown in Fig. 29 for circular milling while the index drive is on, would be stopped by the stud 229 abutting against the end 231 of the rack 227 (Fig. 17). 90

It is obvious from this description that complementary locking mechanisms are provided whereby, when the table is unlocked from stationary engagement with the slide so as to be free to rotate thereon, an engagement of the drive which rotates the table continuously in circular milling locks in inoperative position the drive for partially rotating the table for indexing, and vice versa. 95

Manual engagement of the fast drive 105

As already stated, the fast drive for the reciprocatory movement of the slide 60 and the rotative movement of the work table 61 in milling or advancing the work pieces successively to operative position with the cutter or for returning the reciprocatory slide, is taken from the shaft 5 and transmitted through the shaft 53 (Fig. 26) through the clutch 15 and the gear 13 upon the shaft 5, 110 and the line of gears heretofore described which transmit the rotation to the shaft 53. As also heretofore described, the clutch 15, which thus transmits this fast drive, may be automatically thrown into operation either 115 by dogs, such as the dogs 100 and 101 upon the work table (if that is in rotation) engaging plungers 102 or 103, whereby a clutch shifting throw is transmitted to the rod 111 (Fig. 5), or by dogs upon the slide (if that is 120 being reciprocated), such as dogs 123, 124 similarly operating upon clutch throw rod 111 through plungers 125, 126. It is desirable, however, to also provide a manual operation of the clutch 15, and this is done by a 125 130

5 manual operation of one of the plungers, used in the automatic operation, such as plunger 126 (Fig. 5). As shown in Fig. 8, which is a section on the line 8-8 of Fig. 5, the plunger rod 126 is provided upon a side opposite to that engaging the pinion 108, with rack teeth which are in engagement with a pinion upon a shaft 249, the shaft 249 being provided with a handle 250 (Fig. 1) to permit of its 10 manual rotation. It is obvious that when the shaft 249 is rotated by the handle 250, the plunger 126 is operated, and through the intermeshing lever pinion 108, the clutch throw rod 111 may be operated to either engage or 15 disengage the clutch 15 (Fig. 5).

Combined straight milling and indexing on return

20 As will be understood from the foregoing description of the indexing movement in connection with the movement of the slide 60, a great variety of movements can be derived by setting the different dogs to suit almost any condition and to perform the work in a most economical manner. However, work of a 25 nature which permits the cutters to pass over the work piece entirely, is handled still more economically by performing the indexing movement during the return stroke of the 30 slide.

In this combination of straight milling by the reciprocatory movement of the slide and indexing movement of the table upon the slide, the slow and fast drives are first manually engaged by the hand lever 93 (Figs. 5 and 6) and the hand lever 250 upon the pinion shaft 249 (Figs. 1, 7 and 8), respectively, in the manner heretofore stated. As also already stated, when both the slow and the 40 fast drives are in engagement, because of the differential transmission mechanism shown in plan in Fig. 26, the fast drive is the one effectively transmitted to the shaft 53, and from thence through the shaft 63 (Fig. 27) to drive the slide, and the speed of drive is 45 dropped from high to low by the disengagement of the high speed drive automatically by dogs in the manner heretofore referred to, thus leaving the remaining movement transmitted through the differential mechanism to the shaft 53 that of the slow drive which is similarly transmitted through the shaft 63 to drive the slide at slow speed. Assuming, therefore, that both the slow and fast drives 55 have been engaged by manual operation of the levers 93 and 250, as heretofore stated, the work upon the slide is approaching the cutter rapidly, then the fast drive is automatically disengaged and the movement is slowed 60 down for cutting. After the work has passed through the cutting position, the fast drive is again automatically engaged and the table is speeded up again for traverse, until the next advancing work piece has advanced to 65 cutting relation with the cutter, then the fast

speed is automatically disengaged, and the slide slowed down for the cutting operation, and this succession of drives is continued until all of the successive work pieces have passed through the cutting position.

70 During this period of rapid traverses and slow drives for cutting, work has been fastened to the table on the opposite side of its axis, as shown in the diagram Fig. 32, where the numeral 234 represents either a long piece 75 of work or a series of short pieces of work to be passed through the cutter while the numeral 235 represents a corresponding work piece or plurality of work pieces upon the table 80 upon the opposite side of its axis.

85 After the completion of the cutting operation upon the last work piece, instead of returning the slide and then indexing the table, the table may be speeded up forwardly for a short distance sufficiently to have the last 90 piece of work completely clear the cutter, and then the indexing drive may be engaged by the dog 145 (Fig. 17) in the manner heretofore described, and the return drive for the slide may be engaged by dog 139 (Figs. 1 and 9) in the manner heretofore described, thus causing the return of the slide 95 and the indexing of the table thereon simultaneously.

100 The indexing movement being, for practical purposes, a constant one, is, of course, performed during a certain length of time, and during which time, approximately, the return of the slide should be accomplished. As the length of the return stroke of the slide 105 varies with the length of work to be milled, it follows that the speed of the return movement should be a variable one, for which provision is made by the change gears 32, 33, 34 and 35 (Fig. 26).

110 The effect of returning and indexing simultaneously is clearly shown in the diagrams (Figs. 32, 33 and 34), and, as there shown, the work pieces are, without interference turned around the cutter.

115 In the diagram, Fig. 32, 232 represents the cutter, 233 the circular table in the initial position, 235 the work piece being set, while the cutter is working on 234, 237 the position of the circular table at the end of the feeding movement, 236 the position of the finished work piece 234, 238 the position of the unfinished work piece 235 at the end of the feeding movement.

120 Numerals 16 to 0 indicate the travel of the center of the table on the forward stroke at a feeding rate of speed, that is, at the slow speed, and numerals 0 to 16 the return stroke at a fast rate of speed. The curved line 0a to 16a indicates the path of travel of 125 the point 0a when the table is indexing 180 degrees.

130 Considering now the performance of the indexing and the return movements in approximately the same length of time, and 130

starting both movements simultaneously at the end of the forward feed movement, point 0 will reach point 16, which is the starting position, when point 0a reaches the point 16a, and the unfinished work piece 238 will take the position of the work piece 234, covering in its travel the area indicated by the dotted line 239, and the finished work piece 236 will take the position 235, covering in its travel the area indicated by the heavy line 240. It is particularly to be noted that the diagram shows the work pieces kept at all times clear of the cutter in this indexing and return movement.

Diagram, Fig. 33, shows a slight variation of the arrangement shown in diagram, Fig. 32, the difference being in the different location of the work piece on the table, the work piece being shown as a shorter one than in diagram, Fig. 32. The forward feed and the return fast movement are correspondingly shorter, from 6 to 0 and from 0 to 6, respectively. The speed of the return movement, however, will here be slower in order to give time for the indexing movement during that return, as the indexing movement is constant. To keep the rate of speed for the return movement constant and vary the speed for the indexing movement would not be practical, as then the indexing movement, for, for example, 180 degrees, would reach an excessive rate of speed to perform it in the short time required for short return movement. In Fig. 33, as in Fig. 32, during the return and indexing movements, the work pieces, both finished and rough, are kept clear from the cutter.

Diagram, Fig. 34, shows the method of use of the machine when a still greater number of work pieces are distributed upon the table in a circular path, requiring a separate indexing movement to bring each work piece successively into that path which, by reciprocation of the table when locked to the slide, will pass the work piece beneath the cutter. In Fig. 34, six work pieces are distributed symmetrically about the center of the table; and six indexing movements are required to bring each work piece successively, upon the return of the slide to its initial position, into such position that upon the next advance of the slide and table, the newly positioned work piece will pass beneath the cutter.

In Fig. 32 two work pieces or their equivalent in two rows of work pieces were placed upon the table, and, as heretofore stated, an indexing movement of 180 degrees was required to position the new work pieces in that path which, upon the next advance of the table, would carry the new work pieces beneath the cutter. Similarly where, as in Fig. 34, six work pieces are symmetrically placed upon the table, each indexing movement would be 60 degrees. Assuming now that the time required for indexing the 180

degrees, as in the method of use illustrated in Fig. 32, is 10 seconds, which is also the time required for the return movement of the slide if that slide is to be returned during the period of indexing, regardless of the length of this return movement, it is obvious that the time required for an indexing movement of 60 degrees in the method of use illustrated in Fig. 34 would be only one-third of the time required for indexing 180 degrees, or $3\frac{1}{3}$ seconds. If the return movement of the slide is to be made within the period of this indexing movement, the return movement would, therefore, be required to be three times as fast as the return movement when indexing 180 degrees.

The gears 33, 34, 35 and 36 (Fig. 26) are correspondingly changed to provide for such greater speed.

It will be realized from the foregoing description that the method of milling by a reciprocation of the slide and indexing of the work table thereon, the movements of which are illustrated by Figs. 32, 33 and 34, is a continuous method of milling in a straight line, the work pieces being set and removed while the cutter is working on others; and it is especially the simultaneous indexing and return movement which results in the great saving of time of operation.

Hand drive of the slide and table

Feed screw 63 (Figs. 12 and 27) for the movement of the slide 60, and shaft 86 for the movement of the circular table 61, may be driven also by hand, using the hand wheel 241 (Figs. 1 and 27), from which motion is transmitted over shaft 242, bevelled gears 243 and 244 (Figs. 3, 12 and 27) to gear 92 and gear 65, resulting in a movement of the slide 60 or table 61, depending upon which of the clutches 67 or 158, respectively, is engaged. For the operation of these clutches hand levers are provided conveniently located to the operator. The clutch 158 is operated by hand lever 245 and clutch 67 is operated by hand lever 246 (Figs. 1 and 12). In addition, clutch 71 (Fig. 26), transmitting rotation from shaft 53 to gear 68, is hand operated by hand lever 247 (Fig. 1).

Whenever the hand drives for the slide and table are used, clutch 71, which transmits the power drive from shaft 53, will be kept disengaged to separate the train of gears required for the power drive from the gears required for the hand drive, thus facilitating an easy operation of the latter.

For setting-up purposes, main feed shaft 5, from which all driving movements are derived, is provided with the clutch teeth 248 (Fig. 5) which may be engaged by a co-operative clutch toothed crank handle (not shown) to facilitate all movements of the slide and table derived by hand.

The setting of the dogs in their proper positions required for the work and the method of milling employed is therefore, made easy and convenient for the operator.

- 5 The operation of my improved milling machine has been set forth in connection with the foregoing description of the details thereof, and it is not believed that an additional and formal statement of its operation 10 is essential to understand the principles of my invention as embodied in the machine or in the methods of milling thereby. One other method of milling which may be performed and which has not been specifically 15 set forth, however, is within the contemplation of my invention. Assuming that the work table is in one of the end positions of its reciprocatory movement,—for example, the position indicated by numeral 233 20 (Fig. 32), and with two work pieces to be milled placed symmetrically thereon with respect to the center of the table, as indicated by the numerals 234 and 235,—the work table is advanced from the position 25 233 to the position 237 past and beyond the cutter, during which advance the work piece 234 on the table in line with the cutter is milled and finished. Then at the extreme position 237 of the straight-line path opposite 30 the initial position 233, and before beginning the return in the straight-line path, the work table is indexed to interchange the positions 238 and 236 of the unfinished and finished work pieces, so that the unfinished work 35 piece is brought into the straight-line path with the cutter. The work table is then returned—or, in other words, advanced toward its initial position 233, during which movement the theretofore unfinished work 40 piece is milled, and also during which movement the work piece finished upon the first mentioned advance is removed and a new work piece substituted. When the initial 45 position 233 is again attained, the cycle of movements is repeated by first indexing the table to interchange the positions of the last finished and unfinished work pieces, and by again advancing the table for straight-line milling and by again during such advance 50 removing the last finished work piece and substituting a new work piece therefor. This method of milling, it is to be observed, is a practically continuous one, and very economical in the saving of time, the only time 55 lost from the straight-line movement of the table in straight-line milling being the indexing movement of the table at the opposite extremities of the straight-line path.

Having particularly described my invention, what I claim and desire to secure by Letters Patent is:

1. In a milling machine, a cutter, a work table, means for bodily reciprocating one of said parts relative to the other to cause said cutter to describe a straight-line path across

said work table, means adapted to be actuated into operation for imparting rotary movement to said work table, and means operated by rectilinear movement of said reciprocating part in either direction of its reciprocation to actuate said second mentioned means into operation. 70

2. In a milling machine, a cutter, a work table, driving mechanism for reciprocating said work table, separate driving mechanism 75 for rotatably indexing said work table adapted to be actuated into operation, and means operated by rectilinear movement of said work table in either direction of its reciprocation to actuate said separate driving mechanism into operation. 80

3. In a milling machine, a cutter, a work table, mechanism for imparting reciprocatory movement to said work table, mechanism for imparting a rotary movement to said table, said second mentioned mechanism having a part manually movable to throw said second mentioned mechanism into and out of operation, lock means normally in operative position to prevent rotary movement 90 of said table and movable to inoperative position, and means actuated by said part in its movement to throw said second mentioned mechanism into operation to move and retain said lock means in inoperative position. 95

4. In a milling machine, a cutter, a table mounted for reciprocatory and rotary movements, driven mechanisms to reciprocate and to rotate said table, alternative slow and fast driving means adapted to be connected to each of said mechanisms and means automatically operated in accordance with the table movements for effecting the alternative slow and fast operation of said driving means. 100

5. In a milling machine, a cutter, a work table mounted for reciprocatory and rotative movements, driven mechanisms for imparting reciprocatory and rotary movements to said table, a single driving shaft, a variable speed transmission mechanism adapted to connect said shaft with each of said driven mechanisms alternately and means cooperating with said variable speed transmission mechanism and automatically operated in accordance with said table movements for effecting change in speed of said table movements. 110

6. In a milling machine, a cutter, a work table, means for moving said work table in a straight path relative to said cutter and at a variable speed, means for moving said work table to cause portions thereof to describe a circular path relative to said cutter and at a variable speed, both said means including driving and driven elements and variable speed transmission mechanism and means cooperating with said variable speed transmission mechanism and automatically op- 120 125 130

erated by the table movements for effecting change in speed of said table movements.

7. In a milling machine, a work table, a cutter mounted above said work table, means for moving said work table in a straight path beneath said cutter and means for moving said work table to cause portions thereof to describe a circular path beneath said cutter, and a common means automatically operated by movement of said work table for reversing the direction of said movements.

8. In a milling machine, a cutter, a work table, means for reciprocating said work table through a cycle including fast forward, slow forward and reverse in the order recited, mechanism for imparting movement in partial rotation to said work table, a shiftable element normally holding said mechanism out of operation and shiftable to throw said mechanism into operation, and means actuated by rectilinear movement of said work table to shift said element to throw said mechanism into operation.

9. In a milling machine, a work table, a cutter mounted above said work table to one side of the center thereof, means for reciprocating said work table through a cycle including fast forward, slow forward and reverse in the order recited and past said cutter to bring a work-supporting portion of said table on the same side of its center as said cutter in a straight-line path beneath and beyond said cutter and back to initial position, index means for imparting successive partial rotations to said table about said center to bring work-supporting portions of said table distributed about said center successively into the path described by the straight-line movement of said first mentioned work-supporting portion, and means operated by movement of said table in said straight-line path to operate said index means during each of said reciprocatory table cycles.

10. A mechanism for effecting a feed and a quick traverse, comprising a table, a single driving mechanism for said table, a differential gear connected to said driving mechanism, a power shaft, a relatively slow transmission and a relatively fast transmission between said power shaft and said differential gear, and clutch mechanisms adapted to connect said transmissions with said power shaft and said differential gear.

11. A mechanism for effecting a feed and a quick traverse, comprising, in combination, a table, driving mechanism for said table, a differential gear mechanism connected to said driving mechanism, a power shaft, a relatively slow transmission and a relatively fast transmission between said power shaft and said differential gear mechanism, and clutch mechanisms adapted to connect said transmissions with said power shaft and said differential gear mechanism.

12. In a milling machine, a cutter, a work

table mounted for reciprocatory and rotary movements, a driving shaft for said reciprocatory movement, a driving shaft for said rotary movement, a power shaft, a shaft intermediate said power shaft and said driving shafts and means to simultaneously or alternately connect said intermediate shaft to said driving shafts, and a relatively slow speed transmission and a relatively fast speed transmission extending from said power shaft and adapted to be alternately connected to said intermediate shaft.

13. In a milling machine, a cutter, a work table mounted for reciprocatory and rotary movements, a driving shaft for said reciprocatory movement, a driving shaft for said rotary movement, a power shaft, a shaft intermediate said power shaft and said driving shafts and means to simultaneously or alternately connect said intermediate shaft to said driving shafts, a relatively slow speed transmission and a relatively fast speed transmission extending from said power shaft and adapted to be alternately connected to said intermediate shaft and reversing mechanism for reversing the direction of movement imparted to said intermediate shaft.

14. In a milling machine having a movable support the combination of a motion reverser, a transmission having relatively slow feed motion, a transmission having relatively fast quick traverse motion, each of said transmissions being connectible to actuate said support through said motion reverser, means for connecting said slow transmission to actuate said support at a feed rate and exclusive of said fast transmission, and means for connecting and disconnecting said fast transmission to actuate said support while maintaining said connection of said slow transmission, the last mentioned means including a plurality of dogs adjustably fixed on said support and respectively operable during support movement for said connection and disconnection of said fast transmission.

15. An automatic table propelling mechanism combining a movable table, two members mounted adjacent said table, each for separate movement to one position and provided with a contact surface, a first dog movable with said table adapted to impact a contact surface on one of said members to move said member into said one position, a second dog movable with said table adapted to impact the contact surface on the other of said members to move the other of said members into said one position, a propelling mechanism for imparting slow or fast speed to said table, and a single shift mechanism controlled by said members and adapted in the one position of one of said members to cause said propelling mechanism to slowly advance said table and in the one position of the other said member to rapidly advance said table.

16. An automatic table propelling mecha-

- nism combining a rotatable table, two members adjacent said table, each provided with a contact surface, a first dog movable in a circular path by said table adapted to impact a contact surface on one of said members to move said member into one position, a second dog movable in a circular path by said table adapted to impact the contact surface on the other said member to move the other said member into one position, a propelling mechanism for imparting slow or fast speed of rotation to said table, and a shift mechanism controlled by said members and adapted to the one position of one of said members to cause said propelling mechanism to slowly rotate said table and in the one position of the other of said members to rapidly rotate said table.
17. In a milling machine, a cutter, a work table mounted for movement in a straight path relative to said cutter and for rotation upon an axis eccentric to said cutter, table propelling mechanism for said straight-line movement, table propelling mechanism for said rotary movement, a driving mechanism shiftable to impart slow or fast speed to said table and clutch mechanism adapted to alternately connect said driving mechanism to each of said table propelling mechanisms to alternatively advance said table in said straight-line and said rotary movements, a shift mechanism for said driving mechanism, and means operable by the movement of said table in said straight-line or said rotary movement to operate said shift mechanism.
18. In a milling machine, a cutter, a table mounted for reciprocatory movement past said cutter, and for rotary movement upon an axis eccentric to said cutter, table propelling mechanism for said reciprocatory movement, table propelling mechanism for said rotary movement, a driving mechanism for imparting slow or fast speed to said table and clutch mechanism adapted to alternately connect said driving mechanism to each of said table propelling mechanisms to alternatively reciprocate and rotate said table, a shift mechanism adapted in one position to cause said driving mechanism to slowly advance said table and in another position to cause said driving mechanism to rapidly advance said table, members movable to shift said shift mechanism to the said one and the other positions extending into the path of movement of said table in the reciprocation and rotation of said table, and dogs movable with said table in its reciprocatory and rotary movements to contact and move said members.
19. In a milling machine, a table mounted for movements in opposite directions in a rectilinear and in a circular path, propelling mechanisms shiftable to impart slow or fast speeds to said table in said paths of movements, shiftable reversing mechanism, and shift mechanisms for said propelling and re-
- versing mechanisms adapted to be operated by movements of said table.
20. In a milling machine, a table mounted for movements in opposite directions in a rectilinear and in a circular path, propelling mechanisms shiftable to impart slow or fast speed to said table in said paths of movements, a shiftable reversing mechanism operative for change of table direction in either path, and separate dog controlled shift mechanisms for said propelling and reversing mechanisms and each adapted to be operated by movements of said table.
21. In a milling machine, a table movable in opposite directions in the same linear path, propelling mechanism for imparting a slow or a fast speed to said table, a reversing mechanism shiftable to reverse the direction of movement of said table, means to shift said reversing mechanism including a member movable in opposite directions to effect said shifting, a mounting for said member maintaining the same always in operative position for said movements in opposite directions to effect said shifting, and dogs adjustably mounted upon said table and adapted to contact said member in opposite directions of movement to impart said movements in opposite directions thereto.
22. In a milling machine, a table mounted for reciprocatory and rotary movements, table propelling mechanism for said reciprocatory movement, table propelling mechanism for said rotary movement, driving means for slow and fast speed, clutch means for alternatively connecting said slow and fast driving means with either of said table propelling mechanisms, trip means for changing the speed of said driving means and means automatically operated by said table movements for operating said trip means.
23. In a milling machine, a table mounted for reciprocatory and rotary movements, table propelling mechanism for said reciprocatory movement, table propelling mechanism for said rotary movement, driving means for slow and fast speed, clutch means for alternatively connecting said slow and fast speed driving means with either of said table propelling mechanisms, trip means for changing the speed of said driving means and means automatically operative in timed relation with either the reciprocatory or rotary movements of said table for operating said trip means.
24. In a milling machine, a table mounted for reciprocatory and rotary movements, table propelling mechanism for said reciprocatory movement, table propelling mechanism for said rotary movement, a single driving shaft, means for imparting alternately a slow and a fast speed to said shaft, and clutch means automatically operating in timed relation with the reciprocatory and rotary movements of said table for connecting said driv-

ing shaft to either of said table propelling mechanisms.

25. In a milling machine, a table mounted for reciprocatory and rotary movements, table propelling mechanisms for said reciprocatory and rotary movements, slow speed driving means and fast speed driving means, clutch means for connecting said slow and fast speed driving means for either table movement, other clutch means shiftable for alternatively effecting the one or the other of said speeds, reversing mechanism shiftable to reverse the direction of said slow and fast speed driving means, and shifting mechanisms including dogs adjustably mounted to be operated in accordance with movements of said table to shift said other clutch means and reversing mechanism.

26. A speed change mechanism of the nature disclosed comprising a slow speed shaft adapted to rotate in one direction, a gear frame mounted for rotation upon an axis coincident with the axis of said slow speed shaft in a direction opposite to the direction of rotation of said slow speed shaft, a second shaft mounted for rotation upon an axis coincident with the axis of rotation of said gear frame, gears upon said shafts intermeshing with gears in said frame, driving mechanism adapted to rotate said second shaft at high speed relative to said first mentioned shaft, and in a direction of rotation opposite to the direction of rotation of said first mentioned shaft, and a clutch mechanism for connecting and disconnecting said driving mechanism from said second mentioned shaft.

27. A speed change mechanism of the nature disclosed, comprising a slow speed shaft adapted for rotation in one direction, a second shaft, a transmission mechanism adapted to impart a like speed of rotation from said slow speed shaft to said second shaft but in an opposite direction, said transmission mechanism comprising a gear on each of said shafts and intermediate gearing intermeshing with each of said gears on said shafts, and capable of revolution on said gear on said slow speed shaft in a direction opposite to the direction of rotation of said shaft, a driving mechanism adapted to rotate said second mentioned shaft at relatively high speed in a direction opposite to the direction of rotation of said slow speed shaft, and clutch mechanism for connecting and disconnecting said driving mechanism from said second shaft.

28. A speed change mechanism of the nature disclosed, comprising a slow speed shaft adapted to rotate in one direction, a second rotatable shaft, a gear on each of said shafts, a gearing intermeshing with the gears on said shafts and revolvable thereon, means for restraining said gearing from revolution in the direction of rotation of said slow speed shaft, a driving mechanism for rotating said

second shaft at relatively high speed in a direction opposite to the rotation of said slow speed shaft, and a clutch mechanism for connecting and disconnecting said driving mechanism from said second shaft.

29. In a milling machine, a work driving mechanism therefor, a power shaft, a slow speed shaft, reducing gearing and a clutch mechanism adapted to connect and disconnect said slow speed shaft with said power shaft for rotation in one direction, a second shaft, a gear on each of said shafts, a gearing intermeshing with the gears on said shafts and revolvable thereon, means for restraining said gearing from revolution in the direction of rotation of said slow speed shaft, gearing and a clutch mechanism to connect said second shaft with said power shaft for rotation at high speed in a direction opposite to that of said slow speed shaft and to disconnect said second shaft from said power shaft, and means connecting said second shaft with said driving mechanism.

30. In a milling machine having a reciprocal support, the combination of a motion reverser, a transmission having relatively slow feed motion, a transmission having relatively fast quick traverse motion, means for connecting said slow transmission to actuate said support through said reverser at a feed rate and exclusive of said fast transmission, and means for connecting and for disconnecting said fast transmission to actuate said support through said reverser while maintaining said connection of said slow transmission.

31. In a milling machine having a movable support the combination of a motion reverser, a transmission having relatively slow feed motion, a transmission having relatively fast quick traverse motion, each of said transmissions being connectible to actuate said support through said motion reverser, means operable to connect said slow transmission to actuate said support at a feed rate exclusive of said fast transmission, means operable to connect and to disconnect said fast transmission while maintaining said connection of said slow transmission and control means including dogs adjustably fixed on said support and respectively operable on said means to connect and to disconnect said fast transmission and another dog fixed on said support to completely interrupt movement thereof.

32. In a milling machine having a reversibly movable support the combination of a motion reverser, a transmission having relatively slow feed motion, a transmission having relatively fast quick traverse motion, each of said transmissions being connectible to actuate said support through said motion reverser, means operable to connect said slow transmission to actuate said support at a feed rate exclusive of said fast transmission, means operable to connect and to disconnect said fast transmission while maintaining said connec-

tion of said slow transmission, control mechanism including dogs adjustably fixed on said support and adapted during support movement to operate the last mentioned means to 5 connect and disconnect said fast transmission, and another dog fixed on said support and adapted to operate said motion reverser.

33. A speed change mechanism of the nature disclosed, combining a travelling support, a slow and a fast drive therefor, a pair of control mechanisms for said drives, the one mechanism being adapted in alternative positions to cause said support to travel rapidly and slowly when said other mechanism is in a predetermined position, dogs on said support adapted to move said first mentioned mechanism alternately into its fast and slow positions, and another dog on said support adapted to move said first mentioned mechanism 20 out of its predetermined position.

34. A mechanism for effecting a feed and a quick traverse, comprising a table, a table propelling mechanism, a slow drive and a fast drive, separately operable clutch mechanisms 25 to connect and disconnect said drives to and from said table propelling mechanism, manually operable means to operate the clutch mechanism for said slow drive to connect said slow drive to said propelling mechanism and 30 a member movable to operate said clutch mechanism to disconnecting position, a second member movable to operate the clutch mechanism for said fast drive in connecting and disconnecting position, a reversing 35 mechanism for said drives and a member movable to operate said reversing mechanism, and dogs upon said table positioned to contact and move said movable members to disconnect said slow drive, connect said fast drive, and operate said reversing mechanism.

35. A speed change mechanism of the nature disclosed, combining a travelling support, a slow and a fast drive therefor and a reversing mechanism for said drives, a pair of control mechanisms for said drives and a control mechanism for said reversing mechanism, one of said pair of control mechanisms being adapted in alternative positions to cause said support to travel rapidly and slowly when the other of said pair of control mechanisms is in a predetermined position, dogs on said support adapted to move said first mentioned control mechanism alternately into fast and slow position, and another dog on said support adapted to move the other of said pair of control mechanisms out of its predetermined position and still another dog on said support adapted to move said control mechanism to operate said reverse mechanism.

36. A mechanism for effecting a feed and a quick traverse, comprising a table, a table propelling mechanism, a differential transmission connected to said table propelling mechanism and adapted to impart different

speeds thereto, a relatively slow drive and a relatively fast drive and clutch mechanism for each of said drives adapted to connect and disconnect said drives to and from said differential transmission, a reversing mechanism in said differential transmission adapted to reverse the direction of transmitted movement, and dogs upon said table positioned in series to operate said clutch mechanism and said reversing mechanism. 75

37. In a milling machine the combination of a work support movable in a predetermined path of movement, a rotatable tool spindle positioned above said support and axially transverse to the path of support movement, a spindle support uprising adjacent said work support and at one side of the path of movement thereof, a transmission having relatively slow feed motion, a transmission having relatively fast quick traverse 80 motion, means for connecting said slow transmission to move said work support, and means for connecting and disconnecting said fast transmission while maintaining said connection of said slow transmission, the last mentioned means including a trip device having a portion positioned adjacent said support at the other side of the path of movement thereof and a plurality of dogs adjustably fixed on said support and respectively adapted to 85 operate said trip device to connect and to disconnect said fast transmission. 90

38. In a milling machine having a support movable in forward and in reverse directions, the combination of a motion reverser, a transmission for relatively slow feed motion, a transmission for relatively fast traverse motion, each of said transmissions being connectible to actuate said support through said motion reverser, means operable to connect said slow transmission to actuate said support at a feed rate and exclusive of said fast transmission, means operable to connect and to disconnect said fast transmission while maintaining said connection of said slow transmission; and control mechanism including manually operable mechanism adapted to establish said forward movement of said support, a dog on said support adapted to operate the last mentioned means to disconnect said fast transmission during said forward movement, a dog on said support adapted to operate said motion reverser at the end of said forward movement, a dog on said support adapted to operate said last mentioned means to connect said fast transmission for fast reverse movement of said support, and a dog on said support adapted to interrupt support movement at the end of said reverse movement thereof. 100 110 115 120 125

39. In a milling machine having a support movable in forward and in reverse directions, the combination of a motion reverser, a transmission for relatively slow feed rate, a transmission for relatively fast traverse rate, each 130

of said transmissions being connectible to actuate said support through said motion reverser, means operable to connect said slow transmission to actuate said support exclusive of said fast transmission, means operable to connect and to disconnect said fast transmission while maintaining said connection of said slow transmission, and control means for said reverser and transmissions including a manually operable means to connect a transmission to start said forward movement of said support, and dog operable means to thereafter effect a change from the one to the other of said rates, to reverse said support and to stop support movement after said reverse movement.

40. In a milling machine, a cutter, a table mounted for straight-line and rotary movement, driving mechanism for said straight-line movement in either direction, driving mechanism adapted while in operation to continuously rotate said table and other driving mechanism adapted to rotate said table through predetermined degrees of rotation.

41. In a milling machine, a cutter, a table mounted for reciprocatory movement past said cutter for straight-line milling, for complete rotary movement upon an axis eccentric to said cutter for circular milling, and for partial rotative movement upon the same axis for indexing, driving mechanism operable at will to simultaneously drive said table in said straight-line and said indexing movement, and driving mechanism operable only when said first mentioned driving mechanism is not in operation for driving said table in complete rotation.

42. In a milling machine, a cutter, a table mounted for reciprocatory movement past said cutter for straight-line milling, for complete rotation for circular milling and for partial rotation for indexing, driving mechanisms for moving said table in said straight line milling, said circular milling, and said indexing, means manually operable to throw said driving mechanisms into and out of operation and other means operated by the movements of said table for automatically throwing the driving mechanism for indexing into and out of operation.

43. In a milling machine, a cutter, a table mounted for reciprocatory movement past said cutter for straight-line milling, for complete rotary movement for circular milling, and for partial rotative movement for indexing, driving mechanisms for said straight-line milling, said circular milling and said indexing, and means to throw said driving mechanisms into and out of operation, the means to throw said indexing driving mechanism into operation being adapted to lock said circular milling driving mechanism in inoperative position.

44. In a milling machine, a cutter, a table

mounted for reciprocatory movement past said cutter for straight-line milling, for complete rotary movement for circular milling, and for partial rotative movement for indexing, driving mechanisms for said straight-line milling, for said circular milling and said indexing, and means to throw said driving mechanisms into and out of operation, the means to throw said circular milling driving mechanism into operation being adapted to lock said indexing driving mechanisms in inoperative position.

45. In a milling machine, a cutter, a table mounted for reciprocatory movement past said cutter for straight-line milling, for complete rotation for circular milling, and for partial rotation for indexing, driving mechanisms for moving said table in said straight-line milling, said circular milling and said indexing, and means to throw said driving mechanisms into and out of operation, the means to throw either said circular milling driving mechanism or said indexing driving mechanism into operation being adapted to lock the other in inoperative position.

46. In a milling machine, a cutter, a work table mounted for reciprocatory movement past said cutter for straight-line milling and for rotative movement for indexing, driving mechanisms for said straight-line milling and said indexing, means manually operable at will for throwing said indexing driving mechanism into operation, and means operated in accordance with the movement of said table in said reciprocatory path to automatically throw said indexing driving mechanism into operation.

47. In a milling machine, a cutter, a work table mounted for reciprocatory movement of a work supporting portion thereof past said cutter for straight-line milling and for rotative movement for indexing, driving mechanism for said reciprocatory movement in a cycle including fast forward, slow forward and reverse in the order recited, a constant speed driving mechanism for said rotative movement normally out of operation and adapted to be actuated into operation, and means automatically operated in accordance with rectilinear movement of said table for actuating said constant speed driving mechanism into operation.

48. In a milling machine, a cutter, a work table mounted for reciprocatory movement of a work supporting portion thereof past said cutter for straight-line milling and for rotative movement for indexing, mechanisms to drive said table for said straight-line milling and said indexing, means automatically operated in accordance with the movement of said table in said straight line for throwing said indexing mechanism into operation and means automatically operated by the movement of said table in rotation for throwing said indexing mechanism out of operation.

49. In a milling machine, a cutter, a work table mounted for reciprocatory movement of a work supporting portion thereof past said cutter for straight-line milling and for rotative movement for indexing, mechanisms to drive said table for said straight-line milling and said indexing, means manually operable at will to throw said indexing mechanism into operation and means automatically operated by the indexing movement of said table for throwing said indexing mechanism out of operation.

50. In a milling machine, a cutter, a support mounted for reciprocatory movement past said cutter, a work table mounted upon said support for rotation, driving mechanisms for reciprocating said support to move said table therewith for straight-line milling, driving mechanism for completely rotating said table upon said support for circular milling, and driving mechanism for partially rotating said table upon said support for indexing said table, locking mechanism normally in position to lock said table immovable relative to said support, and means manually operable at will for moving said locking mechanism to unlocking position.

51. In a milling machine, a cutter, a support mounted for reciprocatory movement past said cutter, a work table mounted upon said support for rotation, driving mechanism for reciprocating said support to move said table therewith for straight-line milling, driving mechanism for completely rotating said table upon said support for circular milling, and driving mechanism for partially rotating said table upon said support for indexing said table, locking mechanism normally in position to lock said table immovable relative to said support and means automatically operated in accordance with the movement of said support in its straight-line travel for moving said locking mechanism to unlocking position.

45 52. In a milling machine, a cutter, a support mounted for reciprocatory movement past said cutter, a work table mounted upon said support for rotation, driving mechanism for reciprocating said support to move said table therewith for straight-line milling, driving mechanism for completely rotating said table upon said support for circular milling, driving mechanism for partially rotating said table upon said support for indexing said table, locking mechanism normally in position to lock said table immovable relative to said support and means automatically operated in accordance with the movement of said support in its straight-line travel for moving said locking mechanism to unlocking position, and means associated with and operated by said locking mechanism in its movement to unlocking position to lock said driving mechanism for said indexing in inoperative position but permitting the operation of said

driving mechanism for said rotation of said table for circular milling.

53. In a milling machine, a cutter, a support mounted for reciprocatory movement past said cutter, a work table mounted upon said support for rotation, driving mechanism for reciprocating said support to move said table therewith for straight-line milling and in a cycle including fast forward, slow forward and reverse movement in the order recited, driving mechanism for completely rotating said table upon said support for circular milling, driving mechanism for partially rotating said table upon said support for indexing said table, locking mechanism normally in position to lock said table immovable relative to said support and means automatically operated in accordance with the movement of said support in its straight-line travel for moving said locking mechanism to unlocking position.

54. In a milling machine, a cutter, a support mounted for reciprocatory movement past said cutter, a work table mounted upon said support for rotation, driving mechanism for reciprocating said support to move said table therewith for straight-line milling and in a cycle including fast forward, slow forward and reverse movement in the order recited, driving mechanism for completely rotating said table upon said support for circular milling and alternately at relatively slow and at relatively fast rates, driving mechanism for partially rotating said table upon said support for indexing said table, locking mechanism normally in position to lock said table immovable relative to said support, and means automatically operated in accordance with the movement of said support in its straight-line travel for moving said locking mechanism to unlocking position.

55. In a milling machine, a cutter, a table mounted for reciprocatory movement past said cutter for straight-line milling, for complete rotation for circular milling, and for partial rotation upon said axis for indexing, separate driving mechanisms for said three movements, a single driving shaft and transmission mechanism adapted to impart movement to said driving mechanisms from said driving shaft.

56. In a milling machine, a cutter, a table mounted for reciprocatory movement past said cutter for straight milling, for complete rotation for circular milling, and for partial rotation upon an axis eccentric to said cutter for indexing, separate driving mechanisms for said three movements, a single driving shaft and transmission mechanism adapted to simultaneously or alternately connect said driving shaft with the mechanism for driving said table in straight-line milling and indexing and to singly connect said driving shaft with driving mechanism for circular milling.

57. In a milling machine, a cutter, a table mounted for reciprocatory movement past said cutter for straight-line milling, for complete rotation for circular milling and for 5 partial rotation upon said axis for indexing, separate driving mechanisms for moving said table in said three movements, a single constant speed driving shaft, transmission mechanism adapted to impart alternative fast and 10 slow speeds to said driving mechanisms for said straight-line and circular driving mechanisms from said single driving shaft and transmission mechanism adapted to impart a constant speed to said driving mechanism for 15 said indexing from said single driving shaft.
58. In a milling machine, a cutter, a table mounted for reciprocatory movement past said cutter for straight-line milling, for complete rotation for circular milling, and for 20 partial rotation upon said axis for indexing, driving mechanisms for each of said movements, a constantly rotating prime mover shaft, a variable speed transmission mechanism extending from said prime mover shaft, 25 clutch mechanism operable to connect said variable speed transmission to said driving mechanism for said reciprocatory movement and said driving mechanism for said complete rotation of said table, and a constant speed transmission mechanism operable to 30 connect said prime mover shaft to said indexing driving mechanism.
59. In a milling machine, a cutter, a support mounted for reciprocatory movement 25 adjacent said cutter, a table mounted on said support for rotary movement, means for reciprocating said support, a circular gear rotatable with said table, a second gear journaled for rotation and bodily translatable 40 with said support and adapted to co-act with said circular gear to rotate said table, means to rotate said second gear including a shaft rotatably mounted parallel to the direction of movement of said support, power means 45 for actuating said reciprocating means and said shaft; and control mechanism operative for a predetermined partial rotation of said table from said shaft during a predetermined partial reciprocatory movement of said support.
60. In a milling machine, a cutter, a support mounted for reciprocatory movement adjacent said cutter, a table mounted on said support for rotary movement, means for reciprocating said support in a cycle including a fast forward, a slow forward and a fast reverse movement in the order recited, 55 a circular gear rotatable with said table, a second gear journaled for rotation and bodily translatable with said support and adapted to co-act with said circular gear to rotate said table, a shaft rotatably mounted parallel to the direction of movement of said support and connected to actuate said second gear, power means for actuating said 60
- shaft, and control mechanism operative for a predetermined partial rotation of said table from said shaft during a predetermined portion of the reciprocatory movement of said support. 70
61. In a milling machine, a cutter, a support mounted for reciprocatory movement adjacent said cutter, a table mounted on said support for rotary movement, a nut, a screw mounted parallel to the direction of movement of said support and cooperative with said nut, a power train for reciprocation of said support through said screw and including reversing means, a circular gear rotatable with said table, a second gear journaled for 75 rotation and bodily translatable with said support and adapted to co-act with said circular gear to rotate said table, a shaft rotatably mounted parallel to the direction of movement of said support and connected 80 to actuate said second gear, said shaft being connectible with said power train at a point unaffected by said reversing means; and control mechanism including an element reciprocable with said support and determinative of the connection of said train with said shaft at a predetermined point in said reciprocatory support movement, and an element rotatable with said table and determinative of the disconnection of said train from said 85 shaft at a predetermined point in said rotary table movement. 90
62. In a milling machine, a cutter, a support mounted for reciprocatory movement past said cutter, a table mounted on said support for rotary movement, relatively rotatable elements mounted axially parallel to the direction of movement of said support for said reciprocatory movement, a circular gear rotatable with said table, a second gear journaled for rotation and bodily translatable 100 with said support and adapted to co-act with said circular gear to rotate said table, a shaft rotatably mounted parallel to the direction of movement of said support and connected 105 to actuate said second gear, a power train connectible to actuate one of said relatively rotatable elements and to actuate said shaft, locking means for preventing rotary movement of said table, control mechanism operative for a predetermined partial rotation of said table from said shaft during a predetermined partial reciprocatory movement of said support, and other control means automatically operative to unlock said locking 110 means before said partial rotation and subsequently to lock said locking means after said partial rotation. 115
63. In a milling machine the combination of a rotatable bodily stationary tool spindle, 120 a milling cutter fixed with said spindle, a work support supported adjacent said tool spindle for straight-line bodily movement in forward and reverse directions in a path transverse to the axis of said spindle and ro- 125 130

- tatably indexible for movement of a work piece fixed with said support into and out of a position to be milled by said cutter during said forward movement, a power transmission for movement of said support in said forward and reverse directions including a portion automatically operable for a relatively fast traverse rate of said support during a first part of said forward movement 5 and for a relatively slow feed rate during a later part of the same forward movement, a power index train connectible for said rotatable index movement of said work support, the mechanism automatically operative in accordance with the bodily movement of said work support to connect said index train and subsequently operative to disconnect said train, said mechanism being operative for said work piece to occupy said milling position during said feed rate part of support movement.
64. In a milling machine the combination of a rotatable bodily stationary tool spindle, a milling cutter fixed with said spindle, a work support supported adjacent said tool spindle for straight-line bodily movement in forward and reverse directions in a path transverse to the axis of said spindle and rotatably indexible for movement of a work piece fixed with said support into and out of a position to be milled by said cutter during said forward movement, a power transmission for movement of said support in said forward and reverse directions including a portion automatically operable for a relatively fast traverse rate of said support during a first part of said forward movement and for a relatively slow feed rate during a later part of the same forward movement, a power index train connectible for said rotatable index movement of said work support, said train being connected to be driven from said transmission at a point unaffected by change of rate of said portion, and control mechanism operative after said support has completed said feed rate part of said forward movement to automatically connect said index train and subsequently operative to disconnect said train for said work piece to occupy said milling position during said feed rate part of support movement.
65. In a milling machine the combination of a rotatable bodily stationary tool spindle, a milling cutter fixed with said spindle, a work support supported adjacent said tool spindle for straight-line bodily movement in forward and reverse directions in a path transverse to the axis of said spindle and rotatably indexible for movement of a work piece fixed with said support into and out of a position to be milled by said cutter during said forward movement, a power transmission for movement of said support in said forward and reverse directions including a portion alternatively operable for a relatively fast traverse rate of support movement or for a relatively slow feed rate, a power train connectible for said rotary index movement of said support, control mechanism for said transmission and automatically operable to effect a first part of said forward movement at said fast rate and a later part of the same forward movement at said slow rate, said control mechanism being selectively operable to change the relative length of said first part and later part of forward movement, and control mechanism automatically operative to connect said indexing train subsequent to said later part of said forward movement and to later disconnect said train after a predetermined index movement.
66. In a milling machine the combination of a rotatable bodily stationary tool spindle, a milling cutter fixed with said spindle, a work support supported adjacent said tool spindle for straight-line bodily movement in forward and reverse directions in a path transverse to the axis of said spindle and rotatably indexible for movement of a work piece fixed with said support into and out of a position to be milled by said cutter during said forward movement, a power transmission for said forward and reverse movement and alternatively operable for a relatively fast traverse rate of forward movement and a relatively slow rate of forward movement, a power index train connectible for said rotatable index movement, control means for change from the one to the other rate of said forward movement, other control means operable for connecting and for disconnecting said index train, a plurality of dogs operable in accordance with said bodily support movement and respectively operable on the first mentioned means for said change of forward rate and on said other means to connect said index train, and another dog operable in accordance with said index movement to disconnect said index train.
67. In a milling machine the combination of a rotatable bodily stationary tool spindle, a milling cutter fixed with said spindle, a work support supported adjacent said tool spindle for straight-line bodily movement in forward and reverse directions in a path transverse to the axis of said spindle and rotatably indexible for movement of a work piece fixed with said support into and out of a position to be milled by said cutter during said forward movement, a transmission for relatively slow feed motion, a transmission for relatively fast traverse motion, means operable to connect said slow transmission for bodily movement of said support exclusive of said fast transmission, means operable to connect said fast transmission for bodily movement of said support while maintaining said connection of said slow transmission, a power train for said rotary index movement of said

support, and control means for said transmissions and train operative to automatically effect a cycle including each of said movements of said support.

5 68. In a milling machine the combination of a rotatable bodily stationary tool spindle, a milling cutter fixed with said spindle, a work support supported adjacent said tool spindle for straight-line bodily movement in 10 forward and reverse directions in a path transverse to the axis of said spindle and rotatably indexible for movement of a work piece fixed with said support into and out of a position to be milled by said cutter during 15 said forward movement, automatically power operated means for rotary index movement of said support during said reverse movement thereof, and a power transmission for said bodily movement including a portion automatically operative for a relatively fast 20 traverse rate during a first part of a forward movement, and for a relatively slow feed rate during a later part of the same forward movement and for subsequently effecting 25 said reverse movement at a relatively fast traverse rate.

69. In a milling machine the combination of a rotatable bodily stationary tool spindle, a milling cutter fixed with said spindle, a 30 work support supported adjacent said tool spindle for straight-line bodily movement in forward and reverse directions in a path transverse to the axis of said spindle and rotatably indexible for movement of a work 35 piece fixed with said support into and out of a position to be milled by said cutter during said forward movement, a device shiftable for locking said support against rotary movement and for unlocking said support to permit 40 rotary movement, automatically power operated means for unlocking said device, rotatably indexing said support during said 45 reverse movement and locking said device, and a power transmission automatically operable for relatively fast traverse rate during a first part of said forward movement and for a relatively slow feed rate during a later part of the same forward movement and for subsequently effecting said reverse movement 50 at a relatively fast traverse rate.

70. In a milling machine the combination of a rotatable bodily stationary tool spindle, a milling cutter fixed with said spindle, a work support supported adjacent said tool 55 spindle for straight-line bodily movement in forward and reverse directions in a path transverse to the axis of said spindle and rotatably indexible for movement of a work piece fixed with said support into and out 60 of a position to be milled by said cutter during said forward movement, a device shiftable for locking said support against rotary movement and for unlocking said support to permit rotary movement, automatically 65 power operated means for unlocking said

device, rotatably indexing said support during reverse movement and locking said device, a power transmission operable for either direction of said bodily support movement and for different rates in one direction, and 70 control mechanism for said power transmission including automatically dog operable devices for effecting a change of rate during forward movement of said support and for subsequently changing the direction of support movement.

71. In a milling machine, a cutter, a table mounted for reciprocatory and rotary movements relative to said cutter, table propelling mechanisms for said movements, driving 80 means, clutch means for connecting and disconnecting said driving means with said table propelling mechanisms, and clutch operating means including actuated elements adjacent said table and actuating elements 85 adjustable upon said table adapted in movements of said table to contact said actuated elements to operate said clutch operating means.

72. The method of machine milling upon a milling machine having a reciprocating and a rotatable table and having the cutting tool located to one side of the axis of rotation of said table in all positions of movement of said table, which comprises securing a work piece upon said table to one side of the axis of said table to bring said work piece in cutting relation to said cutting tool in the straight-line travel of said table, securing a succession of additional work pieces upon said table eccentrically to the axis of said table, advancing said table to move said first mentioned work piece past said cutting tool to mill said work piece, returning said table in said straight-line path to initial position and simultaneously with said return partially rotating said table to bring the next of said work pieces into the path described by said first mentioned work piece and again advancing said table to bring said next work piece in said straight-line path into cutting relation with said cutting tool, and repeating said operations of returning, partially rotating and advancing said table until all of said work pieces have successively been milled.

73. In a milling machine, a cutter, a work table, means for reciprocating said work table, mechanism for imparting movement in partial rotation to said work table, a shiftable element normally holding said mechanism out of operation and shiftable to throw said mechanism into operation, and means actuated by rectilinear movement of said work table in either direction of its reciprocation to shift said element to throw said mechanism into operation.

74. In a milling machine, a cutter, a work table, automatic means to impart reciprocatory movement to said work table through a

- cycle including fast forward, slow forward and reverse in the order recited, means to impart rotary index movement to said work table, lock means normally in operative position to prevent rotary movement of said table while permitting reciprocatory movement of said table, and means actuated by said reciprocatory movement of said table to move said lock means to inoperative position. 5
75. In a milling machine, a cutter, a table mounted for reciprocatory and rotary movements relative to said cutter, a table propelling mechanism for said reciprocatory movement, a table propelling mechanism for said 10 rotary movement, a power shaft, transmission means between said power shaft and said propelling mechanisms including movable clutch mechanisms for throwing said table propelling mechanisms into and out of actuation, and clutch moving means operated by rectilinear movement of said table in either direction of its reciprocation to move a clutch mechanism to actuate the propelling mechanism for said rotary movement. 15
76. In a milling machine, a cutter, a work table, automatic means to impart reciprocatory movement to said work table through a cycle including fast forward, slow forward and reverse in the order recited, means to impart 20 rotary index movement to said work table, lock means yieldingly in operative position to lock said table against rotary movement and adapted to be actuated to inoperative position by reciprocatory movement of said table, detent means for holding said lock means in inoperative position during rotary movement of said table, and detent releasing means actuated by rotary movement of said table. 25
77. A combined linear and rotary milling machine comprising the combination of a cutter spindle, a work table adapted to be moved bodily past the spindle in a linear path at cutting speed or to be continuously 30 rotated past the spindle at cutting speed, power means including rate change means selectively operative to either reciprocate the table in its linear path or to continuously rotate the table, and means for automatically controlling both said table movements. 35
78. A combined linear and rotary milling machine comprising the combination of a cutter spindle, a work table adapted to be moved bodily past the spindle in a linear path at cutting speed or to be continuously 40 rotated past the spindle at cutting speed, power means beneath the table and operative either to reciprocate the table in its linear path or to continuously rotate the table, and means for automatically controlling both said table movements. 45
79. A combined linear and rotary milling machine comprising the combination of a cutter spindle, a work table adapted to be moved bodily past the spindle in a linear path 50 at cutting speed or to be continuously rotated past the spindle at cutting speed, means for causing a relative reciprocating movement between the cutter and support, means for automatically rotatably indexing the support during the non-cutting relative reciprocating stroke between the cutter and support, the indexing operation being adapted to place an unmilled piece of work in front of the cutter ready for a milling operation thereon, and automatic means whereby the support may be continu- 55
- at cutting speed or to be continuously rotated past the spindle at cutting speed, power means beneath the table and operative either to reciprocate the table in its linear path or to continuously rotate the table, and means automatically controlling one of the said table movements for intermittently imparting fast and slow speeds to the table in the feeding direction. 60
80. In a milling machine, the combination of a cutter spindle, a work table, power means operative either to reciprocate the table in a linear path or to rotate the table, and means automatically controlling the said rotary table movement for intermittently imparting fast and slow speeds thereto in the feeding direction. 65
81. In a milling machine, the combination of a cutter spindle, a work table, power means operative either to reciprocate the table in a linear path or to rotate the table, and means for automatically controlling either of the said table movements for intermittently imparting fast and slow speeds to the table in the feeding direction. 70
82. A combined linear and rotary milling machine comprising the combination of a cutter spindle, a work table adapted to be moved bodily past the spindle in a linear path at cutting speed or to be continuously rotated past the spindle at cutting speed, power means beneath the table, change speed gearing operated by the power means, and means whereby the power means operates through the said change speed gearing to either reciprocate the table in its linear path or to continuously rotate the table. 75
83. A combined linear and rotary milling machine comprising the combination of a cutter spindle, a work table adapted to be reciprocated bodily past the spindle in a linear path or to be continuously rotated past the spindle at cutting speed, a screw for reciprocating the table, gearing for operating the screw, mechanism for rotating the table, gearing for operating the said mechanism, a power shaft beneath the table, and means whereby the shaft may be operatively connected with either of the said gearing for operating either the screw or the said mechanism from the shaft. 80
84. In a milling machine, the combination of a rotary work support, a spindle adapted to support a milling cutter thereon adjacent the work support, means for causing a relative reciprocating movement between the cutter and support, means for automatically rotatably indexing the support during the non-cutting relative reciprocating stroke between the cutter and support, the indexing operation being adapted to place an unmilled piece of work in front of the cutter ready for a milling operation thereon, and automatic means whereby the support may be continu- 85

ously rotated and alternately at cutting and at non-cutting rates.

85. In a milling machine, the combination of a rotary work support, a spindle adapted to support a milling cutter thereon adjacent the work support, means for causing a relative reciprocating movement between the cutter and support through a cycle including fast forward, slow forward and reverse in 10 the order recited, means for automatically rotatably indexing the support during the reverse portion of the relative reciprocating stroke between the cutter and support, the indexing operation being adapted to place an 15 unmilled piece of work in front of the cutter, ready for a milling operation thereon, means whereby the indexing means may be made inoperative and certain of the second named means be connected to the support to continuously 20 rotate the same, and automatic means operative for alternate fast and slow rates during said continuous rotation.

86. In a milling machine, the combination of a cutter spindle, a work table adapted to be reciprocated bodily past the spindle in a 25 linear path or to be continuously rotated past the spindle at cutting speed, a screw for reciprocating the table, gearing for operating the screw, mechanism including gearing for automatically rotatably indexing the table 30 during the backward reciprocating stroke thereof, a power shaft beneath the table, and means whereby the shaft may be operatively connected with either of the said gearing for 35 operating the screw to reciprocate the table or for operating certain of the said mechanism to continuously rotate the table.

87. In a milling machine, the combination of a work support, a spindle adapted to support a milling cutter thereon adjacent the work support, means for reciprocating the work support and at variable speeds in one direction, means for automatically indexing the support during the backward movement 45 thereof, the indexing operation being adapted to place an unmilled piece of work in front of the cutter ready for a milling operation thereon, and means whereby the said reciprocating means may be connected to the support to automatically and continuously rotate the same at variable speeds.

88. In a milling machine, the combination of a work support, a spindle adapted to support a milling cutter thereon adjacent the work support, means for automatically reciprocating the support and at variable speeds in one direction, and means automatically operative for rotatably indexing the support in synchronism with its backward movement 55 whereby to avoid contact of a previously milled work piece with said cutter during said backward movement, the indexing operation being adapted to place an unmilled piece of work in front of the cutter ready for 60 a milling operation thereon.

89. In a milling machine, the combination of a slide, a rotary work support thereon, a spindle adapted to support a milling cutter thereon adjacent the work support, means for reciprocating the slide, and means for automatically rotatably indexing the support during the reciprocating stroke, the last mentioned means including a device manually adjustable to selectively predetermine a quarter revolution or a half revolution of the support, 70 the indexing operation being adapted to place an unmilled piece of work in front of the cutter ready for a milling operation thereon. 75

90. In a milling machine, the combination of a slide, a rotary work support thereon, a spindle adapted to support a milling cutter thereon adjacent the work support, means for reciprocating the slide, means for locking the support against rotation on the slide and operable for unlocking the support, means for automatically rotatably indexing the support during the backward movement of the slide, the indexing operation being adapted to place an unmilled piece of work in front of the cutter ready for a milling operation thereon, and mechanism for operating the locking means for unlocking the support prior to operation of said means for indexing the support and until the work support is indexed to approximately the desired position. 85

91. In a milling machine, the combination of a slide, a rotary work support thereon, a spindle adapted to support a milling cutter thereon adjacent the work support, means for automatically reciprocating the slide through a forward and backward movement and at a plurality of rates in a forward direction, means for locking the support against rotation on the slide and operable for unlocking the support, means for automatically rotatably indexing the support during the backward movement of the slide, the indexing operation being adapted to place an unmilled piece of work in front of the cutter ready for a milling operation thereon, and mechanism for operating said means for locking the support in accordance with the indexing movement. 90

92. In a milling machine, the combination of a slide, a rotary work support thereon, a spindle adapted to support a milling cutter thereon adjacent the work support, means for automatically reciprocating the slide through a cycle including fast forward, slow forward and reverse in the order recited, means for locking the support against rotation on the slide and operable for unlocking the support, means for automatically rotatably indexing the support during the backward movement of the slide, the indexing operation being adapted to place an unmilled piece of work in front of the cutter ready for a milling operation thereon and mechanism operative in accordance with operation of the indexing means for the unlocking of the 100 105 110 115 120 125

work support prior to operation of the indexing means and the locking of the work support at the end of the desired indexing movement, the said mechanism being adjustable 5 whereby the support may be indexed through different angular distances.

93. In a milling machine, the combination of a slide, a rotary work support thereon, a spindle adapted to support a milling cutter 10 adjacent the work support, means for reciprocating the slide in forward and reverse directions, and at a relatively fast non-cutting rate during a first part of said forward movement and during a part of said reserve 15 movement, and means for automatically rotatably indexing the support during the non-cutting reciprocating stroke, the indexing operation being adapted to place an unmilled piece of work in front of the cutter ready 20 for a milling operation thereon, said indexing means being adjustable for varying the angular rotation of the indexing movement.

94. In a milling machine, the combination of a work table supported for rotary movement on a vertical axis and adapted for supporting a plurality of work pieces spaced apart on the upper table face and adjacent the periphery thereof, a milling cutter rotatably supported above said table and adjacent 25 the table periphery for milling said work pieces one after another during rotation of said table, a transmission alternatively connectible for relatively fast and slow rates of rotary movement of said table, said transmission 30 including means for altering one of said rates exclusive of the other rate, control means for said transmission including a portion adjacent the periphery of said table and shiftable for changing from the one to the 35 other of said rates, and a plurality of dogs spaced apart on said table and each adapted to shift said portion of said control means to change said rate.

95. In a milling machine, the combination of a work table supported for rotary movement on a vertical axis and adapted for supporting a plurality of work pieces spaced apart on the upper table face and adjacent the periphery thereof, a milling cutter rotatably supported above said table and adjacent the table periphery for milling said work pieces one after another during rotation of said table, a transmission alternatively connectible for relatively fast and slow rates 50 of rotary movement of said table and including reversing means adapted to change the direction of table rotation; and control means for said transmission including a first controller for said reversing means, a second 55 controller for alternately connecting said transmission for said fast and for said slow rates, and dogs spaced apart on said table to operate said second controller for alternately effecting said fast and slow rates.

96. In a milling machine, the combination

of a work table supported for rotary movement on a vertical axis and adapted for supporting a plurality of work pieces spaced apart on the upper table face and adjacent the periphery thereof, a milling cutter rotatably supported above said table and adjacent the table periphery for milling said work pieces one after another during rotation of said table, a slow transmission connected for rotary movement of said table, a fast transmission connectible with and disconnectible from said table while maintaining said connection of said slow transmission, and control means for said rotary movement including dogs spaced apart on said table and operable to alternately connect and to disconnect said fast transmission in accordance with table movement. 70

97. In a milling machine, the combination of a rotatable work support adapted for supporting a plurality of work pieces spaced apart adjacent the table periphery, a cutter rotatably supported adjacent said work support and positioned for milling said work pieces one after another during rotation of said work support, a slow transmission connected for rotary movement of said work support, a fast transmission connectible with and disconnectible from said table while maintaining said connection of said slow transmission, and control means automatically operative during rotation of said table to alternately connect and disconnect said fast transmission. 85

98. In a milling machine, the combination of a work table supported for rotary movement on a vertical axis and adapted for supporting a plurality of work pieces spaced apart on the upper table face and adjacent the periphery thereof, a milling cutter rotatably supported above said table and adjacent the table periphery for milling said work pieces one after another during rotation of said table, said table being bodily shiftable in a direction transverse to the axis thereof 100 to adjust the position of the path of movement of said work pieces relative to said cutter and said cutter and table being relatively adjustable in a direction parallel with the axis of said table, a transmission alternatively connectible for relatively fast and slow rates of rotary movement of said table, and including means for altering one of said rates exclusive of the other, and control means for said transmission including dogs adapted during rotary movement of said table to alternately effect said fast and slow rates. 110

99. In a milling machine, the combination of a plurality of supports each movable independently in mutually transverse directions, a rotatable milling cutter, power operated transmission mechanism having portions respectively individual to the different supports, and control means for said transmission. 125

sion for effecting movement of one of said supports through one of said portions exclusive of the other for feeding a work piece in a forward direction in contact with said cutter and for subsequently simultaneously 5 operating both said portions to effect a simultaneous movement of both said supports, said simultaneous movement being effective for relative movement of said work piece and cutter adapted to avoid contact therebetween, 10 said control means including a dog movable with one of said supports and adapted to establish said simultaneous movement.

100. In a milling machine, the combination 15 of a plurality of supports each movable independently in mutually transverse directions, a rotatable milling cutter, power operated transmission mechanism including a portion individual to one of said supports 20 and operable for movement of the last mentioned support in a forward direction for feeding a work piece through a path of milling contact with said cutter and for subsequent movement of said last mentioned support 25 in a reverse direction, and including a portion individual to the other support and operable for movement of said other support adapted to avoid contact of said work and cutter during said reverse direction of movement, and control mechanism for said transmission including a dog on said last mentioned support and adapted to establish said operation of the last mentioned transmission portion.

25 In witness whereof I hereto affix my signature.

ALWIN B. BACHMANN.
